UNITED STATES PATENT OFFICE.

KARL I. HERMAN, OF CHICAGO, ILLINOIS.

BOX-BLANK-MAKING MACHINE.

1,219,941.

Specification of Letters Patent. Patented Mar. 20, 1917.

Application filed August 1, 1912. Serial No. 712,756.

To all whom it may concern:

Be it known that I, KARL I. HERMAN, a citizen of the United States, residing at Chicago, in the county of Cook and State of Illinois, have invented new and useful Improvements in Box-Blank-Making Machines, of which the following is a full, clear, concise and exact description, reference being had to the accompanying drawing forming a part of this specification.

My invention pertains to machinery for feeding, handling, creasing, and cutting sheets of cardboard, fiberboard, and the like; and particularly relates to machines for making the creases and cuts necessary for transforming a sheet of material into a creased and cut blank ready for folding and gluing or riveting, to form a box. It is one of the objects of my invention to produce an efficient and reliable machine which will automatically perform all the operations necessary to transform a sheet of material into a finished box blank ready for folding up to form a box. Another object of my invention is to produce a gradually accelerated device for feeding sheets of material to machinery for operating upon them. It is a further object of my invention to produce an improved device for forming, in a moving sheet, creases which are transverse to the direction of movement of the sheet. It is a still further object of my invention to produce an improved adjustable device for forming simultaneously a plurality of longitudinal creases in a sheet of material. Still another object of my invention is to produce an improved device for forming transverse cuts in register with the transverse creases of a previously creased sheet of material. Yet another object of my invention is to provide a machine in which a sheet is moved through a creasing device, thereby to have transverse creases formed therein, subsequently stopped to receive longitudinal creases, moved forward again, again stopped to receive transverse cuts in register with the transverse creases, and delivered as a finished box blank. And other and further objects of my invention will appear from the following specification, taken in connection with the appended claims.

A machine constructed in accordance with my invention is described, by way of example, in the following specification and

shown in the accompanying drawings, in which:

Figs. 1-4 show successive stages in the production of a finished box blank from a sheet of material.

Figs. 5-8, taken together, form a side elevation of the machine. In these figures, for convenience of description, the front part of the machine is shown as turned forward through one quarter of a cycle from the position it will actually occupy with respect to the remaining part of the machine.

Figs. 9-12, taken together, form a sectional elevation of the machine, the parts being in the positions shown in Figs. 5-8, the section being taken substantially on the line 9-9 of Figs. 13-15.

Figs. 13-15, taken together, form a plan of the machine, the same being upon a smaller scale than Figs. 5-8 and 9-12.

Fig. 16 is a rear view of the front portion 75 of the machine, the same being seen as cut on the line 16-16 of Fig. 13, one of the guide plates being removed so as more clearly to show the feed-rolls.

Fig. 17 is a front view of the portion of 80 the machine, which includes the creaser presses for forming the longitudinal creases, the same being seen as cut on the line 17-17 of Fig. 14.

Fig. 18 is a fragmentary plan showing the 85 transverse drive-shaft and the feed-controlling cams and associated parts, carried thereby.

Fig. 19 is a side elevation of the transverse drive-shaft, the feed-controlling cams 90 carried thereby, the primary feed rolls, and the cam actuated spacing-stop, the same being seen as viewed from the line 19-19 of Fig. 13.

Fig. 20 is a side elevation, partly in section, of the primary feed rolls, the section being taken on the line 20-20 of Fig. 13.

Fig. 21 is a side elevation of the accelerating driving mechanism for the primary feed rolls, the same being seen in a position 100 changed from that shown in Fig. 5, a portion of the bracket bearing being broken away to show more clearly the rack and gears. In this figure the supporting frame is removed so as more clearly to display the 105 parts.

Fig. 22 is an enlarged front view, partly in section, of the ratchet drive for the lower

primary feed roll, the section being taken on the line 22—22 of Fig. 24.

Fig. 23 is a plan of the same.

Fig. 24 is an end view of the same, looking from the left-hand side of Fig. 22, *i. e.*, looking from the side of the machine opposite to that shown in Figs. 5—8.

Fig. 25 is a detail side view of a feed shoe which may be employed in connection with the creaser-reels when short blanks are to be used.

Fig. 26 is a sectional view illustrating the manner of mounting the shoe shown in Fig. 25.

15 Figs. 27 and 28 are detached sectional views illustrating the operation of the creaser-reels when operating upon a short blank.

Fig. 29 is a detail section, on an enlarged 20 scale, of the rotary trimmers, the section being taken on the line 29—29 of Fig. 13.

Fig. 30 is a section on the line 30—30 of Fig. 29, looking in the direction of the arrows.

25 Fig. 31 is an enlarged transverse sectional view showing a portion of the conveyer belts and of a pair of slotter dies, the section being taken on the line 31—31 of Fig. 15.

Fig. 32 is an enlarged fragmentary rear 30 view of the rear part of the machine, with the delivery bands removed, and with the cam housing shown in section, the parts being shown in the position in which the conveyer belt is just about to start to move.

35 Fig. 33 is a rear view of the machine, the same being shown, however, in one of the positions in which the conveyer belts are at rest.

Fig. 34 is a detail view of the ratchet drive 40 for the conveyer belt.

Fig. 35 is a detail plan showing the brake- and clutch-actuating slide.

Fig. 36 is a side elevation of the blank-operated clutch- and brake-controlling trip, 45 showing the same just before being operated to throw out the clutch and apply the brake.

Fig. 37 is a side elevation of the same parts, showing the same in the position which they occupy after being operated, and 50 until the blank has passed away from above the same.

Fig. 38 is a plan of the parts shown in Fig. 36.

Fig. 39 is a detail side view, on an enlarged scale, of the trigger for the trip shown in Figs. 36—38.

Fig. 40 is a transverse section, on an enlarged scale, showing the female-die-carrying beams and the male dies of the creaser-presses, the section being taken on the line 40—40 of Fig. 14.

Fig. 41 is a side elevation of one of the corner-slotters, the same being seen as viewed from line 41—41 of Fig. 15.

65 Fig. 42 is a plan of the same.

Fig. 43 is an end view showing the inner end of the same.

Fig. 44 is an end view showing the outer end of the same, and displaying the means for effecting the spacing adjustment of the 70 slotters.

Fig. 45 is a detail perspective view showing the knives.

Fig. 46 is a side elevation of one of the line-slotters. 75

Fig. 47 is a plan of the same.

Fig. 48 is an end view showing the inner end of the same.

Fig. 49 is a section on the line 49—49 of Fig. 47, looking in the direction of the 80 arrows.

Fig. 50 is an enlarged section on the line 50—50 of Fig. 46, looking in the direction of the arrows.

Fig. 51 is a sectional side view of the corner-slotted shown in Fig. 41 with one portion of the die-supporting arm removed, the section being taken on the line 51—51 of Fig. 15.

Fig. 52 is an enlarged detail sectional 90 view showing the adjustable intermediate supports between the slotters, the section being taken on the line 52—52 of Fig. 15.

Fig. 53 is a plan of the same.

Figs. 54 and 55 are perspective views illustrating the manner of folding up the creased and cut blank to form a box. 95

Figs. 56—59 are diagrammatic views showing the positions of the machine at four successive periods during a cycle thereof, 100 and the locations of the blanks at these periods.

The operations performed by the machine will be readily understood by reference to Figs. 1—4 of the drawings. In Fig. 1 a 105 designates the rough blank (which may consist of a sheet of fiber-board or the like) in the condition in which it enters the machine. The blank is trimmed to a right line at its front edge a^1 , but may have its side and rear 110 edges rough. Fig. 2 shows the blank a after the transverse creases a^2 have been formed therein by the creaser-reels (the arrow showing the direction of its movement through these reels), and after the side edges a^3 have 115 been trimmed to right lines by the rotary trimmers. Fig. 3 shows the blank a after the longitudinal creases a^4 have been formed therein by the creaser-presses. Fig. 4 shows the blank a after the transverse slots a^5 have 120 been formed therein, between the side edges a^6 and the longitudinal creases a^4 and along the transverse creases a^2 , and after the rear corners a^6 have been cut away, the blank being completed, and ready for folding up to 125 form a box. With the machine hereinafter to be described, adjusted as shown in the drawings, the transverse creases a^2 , the longitudinal creases a^4 and the slots a^5 , divide up the blank into two narrow panels a^7 (Fig. 4) 130

having side flaps a^8 , two wide panels a^9 having side flaps a^{10} , and an end flap a^{11} . The blank may be folded in the manner illustrated in Fig. 54, the side flaps a^8 , a^{10} being folded down and secured upon each other, and the end flap a^{11} being secured to the panel a^7 , to form a box of the kind shown in Fig. 55.

Briefly stated, the more prominent features of the construction and operation of the machine shown in the drawings are as follows: The machine includes a bed, which carries the front frame, the laterally adjustable center frames, the supporting arches for the upper conveyer-belt, the bearings for the longitudinal drive-shaft, and other bearings, standards, etc. The front frame is mounted at the front end of the bed, and carries the feed-controlling devices, the accelerating feed mechanisms, the creaser-reels, rotary trimmers, etc. The feed-controlling devices are located at the front end of this frame, and include a feed table, which is provided, at its rear edge, with a spacing-stop against which each blank is placed prior to being fed into the machine. A pair of superposed primary feed rolls, adapted to receive the blank between them, are mounted somewhat in front of the spacing-stop; and mechanism is provided for lowering the top feed roll upon the blank, and removing the spacing-stop from the path of the blank, at the proper time for feeding the same into the machine,—whereby, at the proper time, the blank is clamped between the feed rolls, and the spacing-stop is removed, so that, as soon as the feed rolls begin to rotate, the blank will be moved forward into the machine. The lowering of the upper feed roll and the removal of the spacing-stop from the path of the blank, and the subsequent restoration of these parts to their original positions, is automatically effected at predetermined times in each cycle of the machine. An accelerating feed mechanism is provided for imparting an intermittent rotation to the lower feed roll. This mechanism periodically starts the rotation of the lower feed roll and brings it gradually up to the speed requisite for the proper feeding of the blank, the effect of the several mechanisms so far briefly described being that, immediately the upper feed roll drops upon the blank lying upon the lower feed roll, the spacing-stop is removed from the path of the blank and the lower feed roll begins to rotate slowly, gradually gathering speed, however, until the blank is being fed at the requisite speed. Immediately after leaving the feed table, the forwardly moving blank enters between a pair of rotating creaser-reels, also carried by the front frame. These reels carry interengaging creaser-dies, the dies being arranged transversely to the direction of movement of the blank, so as to

impress the transverse creases a^2 into the material of the blank. As it leaves the creaser-reels, the blank enters between supplementary feed rolls, carried by the front frame, and is carried past a pair of rotary trimmers which trim the side edges a^3 of the blank to right lines. After passing the rotary trimmers, the blank passes between a pair of delivery rolls and onto a pair of feed belts. The feed belts are disposed longitudinally of the machine and travel between suitable side guides against which the edges of the blank engage, so that the blank is kept in proper alignment. The feed belts travel at a greater speed than the feed rolls, and rapidly bring the blank into position to be seized by the longitudinal conveyer-belts. The conveyer-belts are mounted one above the other so that the lower surface of the upper belt lies against the upper surface of the lower belt, the belts being thus capable of gripping the blank between them, as soon as they start to travel. The upper belt is supported on a chain which passes around sprockets carried by supporting arches mounted on the bed, one toward the middle, and one near the end, thereof. The lower belt is supported on a chain which passes around sprockets carried by standards located beneath said arches. These conveyer-belts serve to convey the blank first to the creaser-presses, then to the slotters, and then to the delivery bands; and they are of sufficient length to carry two blanks at a time, one behind the other, the front blank (i. e. the sheet nearer the feed end of the machine) being operated on by the creaser-presses, and the rear blank (which will already have been operated upon by the creaser-presses) being operated upon by the slotters. The conveyer-belts have intermittent forward movements, with intermediate pauses, imparted thereto, the simultaneous effect of each of such movements being (1) to move a blank from the feed belts into position beneath the creaser-presses; (2) to move the blank which has just had the longitudinal creases a^4 pressed therein by the creaser-presses, forward into position beneath the slotters; and (3) to move the finished blank, which had just had the slots a^5 formed therein by the slotters, forward to the delivery bands. During the intermediate pauses of the conveyer-belts, between the intermittent movements thereof, the creasing and slotting operations are simultaneously performed on the separate blanks. It will be noted that the blank should be accurately located with respect to the slotters, when the latter perform their operation, in order that the slots a^5 may coincide properly with the ends of the creases a^2 . This is effected by means of a clutch-tripping and brake-applying device which is set in action by the blank itself as soon as the latter is

brought by the conveyer-belts into the proper position beneath the slotters; the effect being that the conveyer belts are automatically stopped as soon as they have brought a blank into the proper position beneath the slotters. After the conveyer-belts have been thus stopped, and the creaser-presses and slotters have performed their functions, the conveyer-belts are automatically started again so as to move the blank which has just been slotted forward onto the delivery bands, and to move other blanks beneath the creaser-presses and slotters, as described above. The creaser-presses and the slotters are both mounted upon the center frames, of which there are two, one at each side of the machine. These frames carry longitudinal rock-shafts, to which are secured, near the front ends thereof, inwardly-extending arms carrying creaser-beams. The creaser-beams will rise and descend according as the shafts are rocked in one direction or the other. These creaser-beams extend longitudinally of the machine, and carry long female dies, which coöperate with corresponding male dies mounted upon the frames, beneath them. The creaser-beams, by descending, impress the longitudinal creases a^4 in the material of the blank. Each rock-shaft also has four slotted arms secured thereto, adjacent the rear end thereof. These slotted arms carry slotted-blades, adapted to coöperate with dies carried by the center frames, to form the slots a^5 in the blank, and to cut away the corners a^6 therefrom. The slotters may be shifted longitudinally upon the rock-shafts, so as to change the longitudinal distance between the slots a^5 , according to the requirements of the blank being operated upon. The center frames, which carry the creaser-presses and the slotters, are laterally movable upon the bed; and means are provided for the lateral adjustment of the center frames, so as to permit the positions of the longitudinal creases a^4 and of the ends of the slots a^5 to be varied, according to the requirements of the blank being operated upon. The blanks are delivered, in a finished state, upon delivery bands located at the rear end of the machine. The detailed description of the bed, feed-controlling devices, accelerating feed mechanism, creaser-reels, rotary trimmers, conveyer-belts, creaser-presses, slotters, lateral adjustment of the center frames, and delivery bands, will be taken up, as far as possible, in the above order.

The bed.

The bed of the machine (Figs. 5-8 and 9-12) is made up of five sections b^1 , b^2 , b^3 , b^4 and b^5 bolted together so as to form a continuous foundation. The first bed-section b^1 has mounted thereon the front frame, which consists of two standards b^6 and b^7 bolted to the bed-section, one on each side of the machine (Figs. 5, 9, 13 and 16). As has been said, the front frame, constituted by the standards b^6 and b^7 , carries the feed table, the accelerating feed mechanism, the creaser-reels and the rotary trimmers. The front section b^1 of the bed carries bearings for the transverse drive shaft b^9 (Figs. 5, 9, 16, 18, 19 and 21), which actuates the feed controlling mechanism and drives the accelerating feed mechanism. The bed also carries bearings for the longitudinal drive-shaft b^8 , which imparts movement to the conveyer-belts, the creaser-presses, and the slotters, and which is driven, by means of miter gears, from the transverse drive-shaft b^9 . Mounted on the bed sections b^2 and b^5 , are the supporting arches b^{10} and b^{11} , respectively, (Figs. 6, 8, 10, 12, 17 and 33), which carry the bearings for the sprockets of the upper conveyer-belt. Immediately below the supporting arches b^{10} and b^{11} , upon the bed sections b^2 and b^5 , are standards b^{12} and b^{13} , respectively, which carry the bearing supports for the sprockets of the lower conveyer-belt. The bed sections b^3 , b^4 and b^5 are provided with slide-ways b^{14} (Figs. 6, 7, 8, 17 and 32), upon which are adjustably secured the center frames b^{15} and b^{16} , which carry the creaser presses and the slotters.

Feed controlling devices.

Secured to the front part of the front frame, between the standards b^6 and b^7 , is a transverse casting c^1 having a rearwardly projecting lip c^2 , and having secured to the front side thereof a flat support c^3 , the whole, together with the extension plate to be hereinafter described, forming a feed table for supporting the blanks preparatory to their being fed into the machine (Figs. 5, 9 and 13). Mounted upon the frame standards b^6 and b^7 , immediately in front of the lip c^2 of the feed table, are a pair of feed-roller-bearing stands c^4 and c^5 , respectively, which carry bearings for a pair of superposed primary feed rolls c^6 and c^7 , of which the upper roll c^6 is normally held away from the lower roll c^7 , but is automatically lowered thereon at the proper time for feeding a blank into the machine. The feed rolls c^6 and c^7 are provided with interengaging gears, whereby the upper roll c^6 is driven by the lower roll c^7 , when it is lowered thereon.

The automatic raising and lowering of the upper feed roll c^6 is effected by means of a pair of arms c^8 which are pivoted in the bearing-stands c^4 and c^5 . These arms engage, at their rear ends, beneath the lower sides of bearing blocks c^9 which carry the ends of the shaft of the upper feed roll c^6 , and which are mounted so as to be vertically slidable in the bearing stands c^4 and c^5 .

Compression springs c^{10} are provided, which tend to force the upper feed rolls downward (Fig. 20). The arms c^8 have links c^{11} (Figs. 5, 9, 18, 19 and 21) connected with the front ends thereof, the lower ends of these links being connected with arms c^{12} secured to a transverse rock shaft c^{13} mounted in suitable bearings secured to the front frame. One of the arms c^{12} has a pedal c^{14} secured to the front end thereof, to permit the shaft c^{13} to be rocked by the operator, if desired, as will hereinafter be described.

The rock shaft c^{13} has secured thereto a rearwardly and upwardly extending arm c^{15} , the end of which carries a cam roller c^{16} , which engages a cam c^{17} carried by the transverse drive-shaft b^9 . The surface of the cam c^{17} is such that the cam, during its rotation, alternately lowers and raises the cam roller c^{16} . The effect of the lowering of the cam roller c^{16} , is that the shaft c^{13} is rocked so as to cause an upward movement of the links c^{11} , whereby the upper feed roll c^6 is permitted to drop, under the action of the springs c^{10} , upon the lower feed roll c^7 ; and the effect of the raising of the cam roller c^{16} , is to rock the shaft c^{13} in the opposite direction, so as to depress the links c^{11} , and thereby cause the upper feed roll c^6 to be lifted, against the action of the springs c^{10} , away from the lower feed roll c^7 . As the cam c^{17} rotates, therefore, the upper feed roll will alternately be lowered against the lower feed roll, and raised away from the lower feed roll.

Secured between the bearing stands c^4 and c^5 , at the rear of the primary feed rolls, is an extension plate c^{18} , the upper surface of which is flush with the top surface of the casting c^1 (Figs. 9, 13 and 21). This extension plate forms, with the casting c^1 , lip c^2 , and support c^3 , the feed table, upon which the blanks are successively placed preparatory to being automatically fed into the machine. A shaft c^{19} extends transversely beneath the extension plate c^{18} , and is rockably mounted in bearings formed in the feed-roller-bearing-stands c^4 c^5 . The shaft c^{19} has secured thereto a plurality of horizontal rearwardly extending arms c^{20} , to the ends of which is secured a vertical plate c^{21} . The length of the arms c^{20} and the disposition of the plate c^{21} is such that the plate c^{21} extends upward beyond the top surface of the extension plate c^{18} , at the rear end thereof. The plate c^{21} , when the parts are in the position shown in Fig. 9, thus forms a spacing-stop, against which the blanks may be placed preparatory to being automatically fed into the machine. A transverse bar c^{22} extends across the extension plate c^{18} , somewhat above the same, the ends of the bar being secured to the bearing stands c^4 c^5 . Secured to the transverse bar c^{22} are a plurality of downwardly-

rearwardly-extending spring fingers c^{23} which press lightly upon the front edge of the blank, and serve to insure the engagement of the front edge of the blank with the stop-plate c^{21} . It will be seen that if the shaft c^{19} be rocked in a clockwise direction from the position shown in Fig. 9, the stop-plate c^{21} will be moved down below the surface of the extension plate c^{18} , and out of the path of the blank. The position of the stop-plate c^{21} , when the shaft c^{19} has been thus rocked, is shown in Fig. 21.

The intermittent rocking movements of the stop-carrying shaft c^{19} are effected by a cam-actuated lever c^{24} (Figs. 18, 19 and 21), which is pivoted to the inside of the frame standard b^6 . The cam actuated lever c^{24} is connected at its front end, by means of a link c^{25} , with an arm c^{26} which extends rearwardly from the shaft c^{19} . The link c^{25} passes through an ear c^{27} which projects inwardly from the frame standard b^6 , and has a collar secured thereon between which collar and the ear c^{27} is interposed a compression spring c^{28} , the tendency of which is to force the arm c^{26} upward. A cam roller c^{29} is carried by the rear end of the lever c^{24} , and engages a cam c^{30} carried by the transverse drive shaft b^9 . The cam c^{30} effects an alternate upward and downward movement of the cam roller c^{29} . When the cam roller c^{29} is raised, the link c^{25} depresses the arm c^{26} , and thus causes the stop-plate c^{21} to be moved downward out of the path of the blank; and, when the cam roller c^{29} is permitted to fall under the action of the spring c^{28} , the arm c^{26} is raised by the link c^{25} , and the stop-plate c^{21} is restored to its position in front of the extension plate c^{18} .

The cam c^{30} for moving the stop plate, is so arranged with relation to the cam c^{17} for moving the upper feed roll that the stop plate will be depressed at the same moment as the upper feed roll is allowed to fall upon the lower feed roll. As will herein-after be described, the primary feed rolls start to revolve, just after the upper feed roll has been allowed to drop upon the lower, and just after the stop-plate c^{21} has been depressed.

The operation of the feed-controlling devices is as follows: While the upper feed-roll c^6 is raised (Fig. 9), a blank is manually placed on the feed table, with its trimmed front edge a^1 in contact with the stop-plate c^{21} , and one of its side edges in contact with a guide c^{31} which is mounted upon the casting c^1 of the feed table so as to be laterally adjustable thereon. The transverse drive shaft b^9 rotates continuously; and, immediately after the cams carried thereby have passed the position shown in Fig. 19, the upper feed roll c^6 will be allowed to fall upon the lower feed roll, and

105

110

115

120

125

130

the stop plate c^{21} will be moved down out of the path of the front of the blank (Fig. 21). Just at this time the primary feed rolls begin to rotate, and the blank, being gripped between the feed rolls, is thereby fed forward into the machine.

If, for one reason or another, it is desired to stop a blank, the feeding of which into the machine has been started, this may be effected by the operator placing his foot on the pedal c^{14} and depressing the same, the effect being that the upper feed roll will be raised, whereupon the blank can be pulled back.

15 *Accelerating feed mechanism.*

As has been said, immediately the upper feed roll is caused to drop upon the lower feed roll, the latter begins to rotate slowly and gradually increases its rate of rotation until the right peripheral speed for the proper feeding of the blank is reached. Owing to the intermediate gearing, the upper feed roll participates in this rotation. In order to effect this result, the shaft, of the lower feed roll c^7 is provided, at the right hand side of the machine (looking at the front of the machine), with an extension d^1 (Figs. 13, 22, 23 and 24) which rotates in a bracket bearing d^2 secured to the outside of the frame standard b^6 . The shaft extension d^1 has secured thereon a pinion d^3 , having a collar d^4 extending from one side thereof. The periphery of the collar d^4 is cut away so as to form a shoulder d^5 , this collar, formed with its shoulder d^5 , acting as a ratchet wheel having but one tooth. Loosely mounted upon the shaft extension d^1 , between the pinion d^3 and the bearing d^2 , is a pinion d^6 having a bracket d^7 extending radially therefrom so as to project over the collar d^4 . The bracket d^7 is formed with a guide-way, in which is slidably mounted a spring-pressed ratchet block d^8 , which is adapted to ride upon the periphery of the collar d^4 of the pinion d^3 . It will be seen that if the pinion d^6 be rotated in a clockwise direction, as indicated by the arrow, the ratchet block d^8 will ride upon the surface of the collar d^4 until it strikes against the shoulder d^5 , whereupon the pinion d^3 will be caused to take part in the revolution of the pinion d^6 . It will be seen that this construction permits the pinion d^3 to be rotated in a clockwise direction at a faster rate of speed than the pinion d^6 , or to be rotated in a clockwise direction, while the pinion d^6 is rotated in a contraclockwise direction, the only effect, in either case, being that the ratchet block d^8 will snap over the shoulder d^5 , from the rear, each time the pinion d^3 makes a revolution relatively to the pinion d^6 .

Secured to a sleeve d^9 which is loosely mounted on the shaft extension d^1 is a

swinging guide-bracket d^{10} , the lower end of which forms a slide-bearing for a rod d^{11} . The upper end of the rod d^{11} is provided with a rack d^{12} which is guided beneath an over-turned lug d^{13} carried by the bracket d^{10} , so as to engage the teeth of the pinion d^6 . The lower end of the rod d^{11} is connected with a crank d^{14} carried by the transverse drive-shaft b^9 , the connection between the rod d^{11} and the crank d^{14} being such as to permit of adjustment to vary the length of the throw of the crank. The crank d^{14} is secured to the shaft b^9 also, so as to permit of angular adjustment relatively thereto.

The result of the construction so far described is that, as the crank d^{14} rotates in a contra-clockwise direction from the position shown in Fig. 5, the pinion d^6 will be rotated in a clockwise direction during the first half revolution of the crank, during which the rack d^{12} moves downward, and will be rotated in a contra-clockwise direction during the second half revolution of the crank, during which the rack d^{12} moves upward. For purposes which will appear below, the crank d^{14} is so disposed upon the transverse drive-shaft b^9 that it will reach the dead-center position shown in Fig. 5 immediately after the cams c^{17} and c^{18} have effected the lowering of the upper feed roll and the removal of the stop-plate c^{21} from the path of the blank, respectively.

As has been said, the rotation of the crank d^{14} effects a rotation of the pinion d^6 first in a clockwise direction and then in a contra-clockwise direction. It is only the first half of the rotation of the pinion d^6 in a clockwise direction, however, which is utilized for driving the pinion d^3 , the latter being thereafter driven directly from the transverse drive-shaft b^9 . To this end, the pinion d^3 is geared, by means of an intermediate pinion d^{15} , with a toothed wheel d^{16} , which is mounted so as to be freely rotatable upon the lower creaser reel shaft. The toothed wheel d^{16} has secured thereto, so as to be capable of angular adjustment, a mutilated gear wheel d^{17} . The mutilated gear wheel d^{17} has a concavity d^{18} (Figs. 5 and 21) formed at a portion of its periphery, and is adapted to mesh with the teeth of a corresponding mutilated gear wheel d^{19} , which is secured to the transverse drive shaft b^9 . The convex surface d^{20} of the mutilated gear wheel d^{19} , at the part thereof where the teeth are omitted, is adapted to engage in the concavity d^{18} of the mutilated gear wheel d^{17} ; and a portion d^{21} of the periphery of the wheel d^{19} is cut away, so as to permit the wheel d^{17} to rotate as soon as this cut away portion comes into register with the concavity d^{18} .

The operation of the accelerating mechanism is as follows: When the parts are in the position shown in Fig. 19, the cams c^{17} 130

and c^{13} are just about to cause the upper feed roll to drop upon the blank, and to cause the stop plate to move down out of the path of the blank, the crank d^{14} being, at this time, at one of its dead-center positions. The upper feed roll having dropped upon the blank, the crank d^{14} , rotating in the direction of the arrow, begins to move the rack d^{12} downward, and consequently to turn the pinion d^6 in a clockwise direction. This turning movement will at first be slow, owing to the fact that the crank d^{14} is just leaving its dead-center position; but, as the crank moves farther away from its dead-center position, the speed of rotation of the pinion d^6 gradually increases. As the pinion d^6 rotates, it carries the pinion d^3 with it, by reason of the engagement of the ratchet block d^8 with the shoulder d^5 . The gradually accelerating movement of the pinion d^6 , therefore, effects a corresponding gradually accelerating movement of the pinion d^3 . The downward movement of the rack d^{12} also causes the mutilated gear d^{17} to begin to rotate, owing to the connection of this gear with the pinion d^3 through the gear wheel d^{18} and pinion d^{19} . The gear wheel d^{17} is permitted thus to begin to rotate, owing to the fact that the recessed portion d^{21} of the gear wheel d^{19} was opposite to the concavity d^{18} (Fig. 5) when the rack d^{12} began its downward movement. The total result, therefore, of the first portion of the rotation of the crank d^{14} from the position shown in Fig. 5, is that a gradually accelerating rotation is imparted to the pinion d^3 , which latter causes the mutilated gear d^{17} to begin to turn. The position of the parts when the pinion d^3 is approaching its highest speed of revolution, is shown in Fig. 21.

When the crank d^{14} has moved through a right angle from the position shown in Fig. 5, *i.e.*, somewhat beyond the position shown in Fig. 21, the pinion d^3 will have attained its maximum speed, the parts being so arranged that the peripheral speed of the feed roll c^7 so attained will be the correct speed for feeding the blank into the machine. The mutilated gears d^{17} and d^{19} are so formed that their teeth will begin to engage with one another just at the time when the pinion d^3 reaches its maximum speed. As soon as the teeth of the mutilated gears d^{17} and d^{19} have come into engagement, the wheel d^{17} ceases to be driven by the pinion d^3 , and becomes a driving wheel for that pinion. The pinion d^3 is thereafter driven directly from the transverse drive-shaft b^9 , through the gear wheels d^{19} , d^{17} , d^{16} and d^{15} . By reason of this fact, the pinion d^3 will continue to be driven at its maximum speed, in spite of the fact that the pinion d^6 will gradually slow down, and, after the crank d^{14} has passed its other

dead center, will rotate in the opposite direction. After the gear wheel d^{18} has moved through something less than one half a revolution from the point at which its teeth first engage with the teeth of the wheel d^{17} , its convex portion d^{20} will come into register with the concavity d^{18} of the gear wheel d^{17} , which latter will thereafter be locked against rotation, the pinion d^3 being thus stopped while the gear wheel d^{19} completes its revolution. As soon as the parts come again into the position shown in Fig. 5, the gear wheel d^{17} will again be freed, and the above cycle of operations will recur.

It will be seen from the above description that, as soon as the upper feed roll c^6 drops upon the lower feed roll c^7 , the lower feed roll will begin to rotate slowly, its speed being, however, gradually accelerated, until the proper speed for the feeding of the blank is reached. When this speed has been attained, the feed roll will be driven at that speed for a sufficient time to permit the blank to be fed into the machine. It is desirable that the distance through which the blank is moved by the feeding mechanism, between the time when the stop-plate c^{20} first drops and the time when the dies carried by the creaser-reels make the first impression in the blank, be accurately determined. This is effected by my construction of feeding mechanism, since the gearing, etc., is properly chosen so as to give the correct peripheral speed of the feed rolls for the proper feeding of the blank; and slippage of the blank relatively to the feed rolls, which would otherwise be liable to occur owing to the weight of the blank, is avoided by reason of the gradually accelerated movement of the lower feed roll.

Creaser-reels.

As the blank is fed forward into the machine by the feeding mechanism described above, it enters between a pair of superposed creaser-reels f^1 and f^2 , the lower of which reels is mounted upon a transverse shaft f^3 rotatably mounted in bearings carried by the frame standards b^6 and b^7 . The upper reel, f^1 (Figs. 5, 9, 13 and 16) is mounted on a transverse shaft f^4 carried by bearing blocks f^5 which are mounted so as to be capable of vertical adjustment in bearing standards f^6 which extend upward from the frame standards b^6 and b^7 . The creaser-reels f^1 and f^2 are provided with interengaging gear wheels f^7 and f^8 , respectively, by means of which the rotation of the lower creaser-reel is imparted to the upper reel. The lower creaser-reel f^2 derives its rotation from a transverse main shaft f^9 which is mounted in suitable bearings carried by the frame standards b^6 and b^7 , and which carries a pinion f^{10} which meshes with the gear wheel f^8 of the lower creaser reel. The

transverse main shaft f^9 also carries a pulley f^{11} which is adapted to be connected, as by means of a belt or the like, with a suitable source of power. Thus, the rotation of the transverse main shaft f^9 causes the rotation, in opposite directions, of the creaser-reels f^1 and f^2 .

The shaft f^3 of the lower creaser-reel carries, at the outside of the frame standard b^7 , a gear wheel f^{12} , which meshes with a corresponding gear wheel f^{13} which is secured to the transverse driving shaft b^9 , referred to above, the relation of the teeth of the gear wheel f^{12} to those of the gear wheel f^{13} being that of one to two. The creaser-reels thus rotate twice for each revolution of the transverse drive-shaft b^9 . The first revolution of the creaser-reels, *i. e.*, the revolution which occurs while the gear d^{19} of the feed mechanism is making the first half of its revolution from the position shown in Fig. 5, effects the creasing operation. The second revolution of the creaser-reels, *i. e.*, the revolution which takes place during the second half of the revolution of the gear d^{19} , is idle.

The upper creaser-reel f^1 comprises a plurality of wheels f^{14} arranged in pairs side by side, to the peripheries of which are secured four transverse female dies f^{15} , f^{16} , f^{17} and f^{18} , which coöperate with corresponding transverse male dies f^{19} , f^{20} , f^{21} and f^{22} , secured to wheels f^{23} , carried by the shaft f^3 on the lower creaser reel. In order that the dies may be adjusted circumferentially upon the die-supporting wheels, in accordance with the desired distances between the transverse creases of the box blank, they are attached thereto by means of clamping plates f^{24} (Fig. 26), which engage beneath the flanges of the die-supporting wheels. The dies are provided with inwardly-extending bolts which pass through the clamping plates f^{24} and receive nuts f^{25} . After the nuts f^{25} have been loosened, the dies may be moved to any desired circumferential position upon the die-supporting wheels, and may thereafter be secured in that position by tightening the nuts. In order to permit of the accurate positioning of the dies upon the die-supporting wheels, some of these wheels may be furnished with graduation marks f^{26} (Fig. 16).

During the rotation of the creaser-reels, the dies f^{15} and f^{19} of the upper and lower creaser-reels respectively, coöperate to produce the first transverse crease a^2 (at the right-hand side of Fig. 2); the dies f^{16} and f^{20} produce the second transverse crease a^2 ; the dies f^{17} and f^{21} produce the third transverse crease a^2 ; and the dies f^{18} and f^{22} produce the fourth transverse crease a^2 . Owing to the provision of the spacing-stop c^{21} and the construction of the feed mechanism, the front edge a^1 of the sheet will always arrive

at the point of intersection of the creaser-reels so as to register with certain points upon the peripheries of the same; and these points form the zeros from which the graduations f^{26} start. By measuring back from these zero points, distances, along the graduations of each creaser-reel, equal to the distance which is to be between the front edge a^1 of the blank and the first crease a^2 , the position of the dies f^{15} and f^{19} may be accurately determined. The positions of the other dies may be determined in a like manner. As the blank is gripped between the transverse dies of the creaser-reels while its rear part is still being fed forward by the feed rolls c^6 and c^7 , the diameter of the creaser-reels is chosen so that the peripheral speed of the reels will be the same as that of the feed rolls, whereby stretching or buckling of the blank is avoided.

The blanks employed will be of varying thicknesses, and, to meet this condition, means are provided for adjusting the distance between the creaser-reels. To this end, nuts f^{32} are threaded into sockets carried by the upper ends of the bearing stands f^6 . The nuts f^{32} are attached, at their lower ends, to the bearing blocks f^5 of the shaft f^4 of the upper creaser-reel, and are provided at their upper ends with bevel pinions f^{33} . With the bevel pinions f^{33} engage other bevel pinions f^{34} carried by a transverse spindle f^{35} , which is mounted in bearings carried by the stands f^6 . The spindle f^{35} is provided with a hand wheel f^{36} , at one end. By turning the hand wheel f^{36} in one direction or the other, the nuts f^{32} will be turned, with the result that the bearing blocks f^5 will be raised or lowered to effect the desired adjustment of the distance between the creaser-reels.

As the blank is fed forward by the feeding mechanism, it passes between the creaser-reels, and has the transverse crease a^2 impressed therein in the manner described above. After the front part of the blank has passed between the creaser-reels, and before the rear part of the blank has left the feed rolls, the front part of the blank strikes an apron f^{27} , mounted between a pair of bearing stands f^{30} which extend upwardly from the frame standards b^6 and b^7 at the rear of the bearing stands f^6 . The bearing stands f^{30} carry the bearings for a pair of supplementary feed rolls f^{28} and f^{29} , which are driven, by means of intermediate gearing f^{37} , from the gear wheel f^8 of the lower creaser-reel. The apron f^{27} guides the blank between the supplementary feed rolls f^{28} and f^{29} , of which the upper roll, f^{28} , is made up of a plurality of feeding wheels, so as to avoid crushing the creases which have been formed by the creaser-reels. With blanks of normal size, the supplementary feed rolls f^{28} and f^{29} will have seized the sheet before the same has left the primary feed rolls c^6 and c^7 .

The supplementary feed rolls f^{28} and f^{29} move the blanks forward to the rotary trimmers.

In some cases it will be desired to produce, by means of this machine, a blank so short that its front end will not enter the supplementary feed rolls f^{28} and f^{29} before its rear end has left the primary feed rolls c^6 and c^7 . In order to meet such a condition as this, means are provided whereby the creaser reels may themselves be employed as feed rolls. To this end, a plurality of arc-shaped shoes f^{31} (Figs. 25-28) are provided. These shoes are of different lengths, so that the proper sizes may be chosen for filling in the spaces between the transverse dies, and are of sufficient depth so that the blank being creased will be gripped between them. The shoes f^{31} are formed with elongated slots f^{38} therein, through which cap screws f^{39} are passed to enter holes f^{40} (Figs. 9 and 26) which are formed in the sides of the wheels f^{14} and f^{22} of the upper and lower feed rolls, thus permitting longitudinal adjustment of the shoes f^{31} . These shoes form a continuous feeding surface at the periphery of the creaser-reels, and operate to transfer the blank from the primary feed rolls to the supplementary feed rolls, as shown in Figs. 27 and 28 of the drawings.

Rotary trimmers.

As the sheet is moved forward by the supplementary feed rolls f^{28} and f^{29} , it passes between the rotary trimmers, which trim its lateral edges a^8 to right lines. These trimmers are mounted, one at each side of the machine, upon superposed shafts g^1 and g^2 carried by bearing stands g^3 (Figs. 9, 13, 29 and 30). The shafts g^1 and g^2 are geared to the supplementary feed rolls f^{28} and f^{29} so as to be driven thereby. Each rotary trimmer consists of a die wheel g^4 carried by the shaft g^2 , against the edge of which engages a circular knife g^5 carried by a longitudinal movable collar g^6 which is feathered upon the shaft g^1 . A compression spring g^7 is mounted between the collar g^6 and a ring g^8 secured to the shaft g^1 , the tendency of which spring is to force the circular knife g^5 against the side of the die wheel g^4 . An apron g^9 is provided, for guiding the blank between the trimmers. The rotary trimmers are driven at the same speed as the supplementary feed rolls, but are of larger diameter than said feed rolls, the effect being that the peripheral speed of the rotary trimmers is greater than the speed at which the blank is moved into the machine, whereby a proper cutting action is obtained. The trimmer knives g^5 cooperating with the die wheels g^4 , form longitudinal slits in the blanks passing between them, and thereby trim the edges a^8 of the blanks to right lines.

As the blank leaves the rotary trimmers

it is guided, by an apron g^{10} , between a pair of delivery rolls g^{11} and g^{12} mounted in bearings carried by bearing stands g^{13} , the delivery rolls g^{11} and g^{12} and the bearing stands g^{13} being of a similar construction to the supplementary feed rolls f^{28} and f^{29} and the bearing stands therefor. The delivery rolls g^{11} and g^{12} are driven, by suitable gearing, from the rotary trimmers. The delivery rolls deliver the blank, then in the condition shown in Fig. 2, to the feed belts, which latter convey the blank to the conveyer-belts to be carried thereby to the creaser-presses and subsequently to the slotters.

The feed belts h^1 , of which there are two, travel around front pulleys h^2 and rear pulleys h^3 . The front pulleys h^2 are carried by a transverse spindle h^4 which is rotatably mounted in bearings h^5 carried by a vertical standard h^6 which is secured to the bed, between the sections b^1 and b^2 (Figs. 5-6, 9-10 and 13-14). The vertical standard h^6 also carries bearings h^7 for a longitudinal spindle h^8 , to which is secured, at its front end, a bevel gear h^9 which meshes with a bevel pinion h^{10} carried by the transverse spindle h^4 . The longitudinal spindle h^8 is driven by means of a chain h^{11} passing over sprockets carried by the spindle and by the longitudinal drive shaft b^8 , respectively. The gearing of the chain h^{11} is such that the peripheral speed of the pulleys h^2 , and consequently the speed of travel of the feed belts h^1 , will be greater than the speed at which the blank is delivered by the delivery rolls g^{11} , g^{12} . The rear pulleys h^3 , are mounted in bearings carried by arms h^{12} , which are mounted so as to be longitudinally adjustable in the standard b^{12} which carries the front bearing for the lower conveyer-belt. Set screws h^{14} are provided for effecting the longitudinal adjustment of the bearing-arms h^{12} in the standard b^{12} . By moving the bearing arms longitudinally in one direction or the other, by means of the set screws h^{14} , the feed belts h^1 may be tightened or slackened, as desired.

A pair of longitudinal tables h^{15} are secured to the center frames b^{15} and b^{16} and extend forwardly, at the front of the center frames, one on each side of the feed belts h^1 . The blanks, in being fed forward by the feed belts h^1 , slide over the tables h^{15} . These tables extend frontwardly as far as the front pulleys h^2 and rearwardly as far as the rear ends of the creaser presses; and they carry gages for guiding the blank while it is being fed forward by the feed belts, and while it is being moved forward by the conveyer-belts to, and away from, the creaser-presses. These gages consist of long strips h^{16} , which extend longitudinally of the tables h^{15} , from one end of the same to the other. The strips h^{16} are provided with a plurality of upwardly extending ears h^{17} , 150

through which pass screws h^{18} . The outer ends of the screws h^{18} are rotatably mounted in brackets h^{19} secured to the outer sides of the tables h^{15} , and are provided with worm pinions h^{20} . Gage-shafts h^{21} , extending longitudinally of the tables h^{15} , at the outer sides thereof, are rotatably mounted in the brackets h^{19} , and carry worms h^{22} , which mesh with the worm pinions h^{20} carried by the screws h^{17} . The gage-shafts h^{21} are provided, at their front ends, with handles h^{23} , by means of which they may be rotated in one direction or the other, as desired. By rotating the gage-shafts h^{21} in one direction, the gages h^{16} are moved toward each other, over the tables h^{15} , and by rotating the gage shafts h^{21} in the opposite direction, the gages are moved away from each other. By this means, the distance between the gages h^{16} may be varied according to the width of the trimmed blank, so that the latter will be guided in its proper alignment in the machine. The tables h^{15} are preferably graduated, as at h^{24} (Fig. 13), so as to facilitate the setting of the gages to the proper distance apart.

The blank is delivered, by the delivery rolls g^{11} , g^{12} , upon the feed belts h^1 , which carry it over the tables h^{15} , with its side edges a^3 in engagement with the gages h^{16} . The blank will be fed forward by the feed belts, until it is stopped by striking between the conveyer belts, which latter will be stationary at that time. After the blank has thus stopped in engagement with the conveyer belts, it will be held in such engagement, ready to be seized by the conveyer-belts when they begin to move, by reason of the frictional engagement of the feed belts h^1 , which continue traveling beneath the blank. This transferring of the blank from the rotary trimmers to the conveyer-belts is quickly effected, owing to the increased speed of the feed belts h^1 . The feeding of the blank from the rotary trimmers to the conveyer-belts occurs during a portion of the second, or idle, rotation of the creaser-reels.

Conveyer-belts.

The lower conveyer-belt m^1 is secured, as by means of rivets m^2 , to a chain m^3 (Fig. 31), which chain passes around a front sprocket m^4 , and a rear sprocket m^5 (Figs. 6-8, 10-12, and 14-15). The front sprocket m^4 is rotatably mounted in a bearing fork m^6 which is carried by the standard b^{12} . The bearing fork m^6 is longitudinally adjustable in the standard b^{12} , such adjustment being effected by means of a cap screw m^7 . By manipulating the cap screw m^7 , the tension of the chain m^3 and belt m^1 may be varied as desired. The rear sprocket m^5 is secured to a transverse spindle m^8 rotatably mounted in the standard b^{13} at the rear end

of the machine, power being intermittently imparted to the spindle m^8 to cause intermittent forward movements of the conveyer-belt m^1 . A plurality of intermediate supporting sprockets m^9 are interposed between the front sprocket m^4 and the rear sprocket m^5 . These intermediate sprockets are mounted in bearings carried between a pair of longitudinal beams m^{10} , which are mounted upon two supporting standards m^{11} and m^{12} carried by the bed sections b^3 and b^4 , respectively. The function of the intermediate sprockets m^9 is to support the chain m^3 and belt m^1 in a horizontal plane, and to thus prevent the sagging of the belt which otherwise would occur.

The upper conveyer-belt m^{13} is secured to a chain m^{14} in a similar way to that in which the lower belt m^1 is secured to the chain m^3 . The chain m^{14} passes around a front sprocket m^{15} which is carried by a bearing fork m^{16} , mounted in the front supporting arch b^{10} . A cap screw m^{17} is provided for effecting the longitudinal adjustment of the bearing fork m^{16} in a manner similar to that in which the longitudinal adjustment of the bearing fork m^6 is effected by the cap screw m^7 . The chain m^{14} also passes around a rear sprocket m^{18} , which is rotatably mounted in a bearing fork m^{19} carried by the rear supporting arch b^{11} , in a similar manner to that in which the front sprocket-supporting fork m^{16} is carried by the supporting arch b^{10} . There is no driving connection for the upper chain and belt, this chain and belt traveling only 100 by reason of the engagement of the belt m^{18} with the blanks carried by the traveling-belt m^1 . A plurality of intermediate sprockets m^{20} are interposed between the front sprocket m^{15} and the rear sprocket m^{18} . 105 These intermediate sprockets have no bearings, being held in place merely by reason of the engagement of their teeth with the links of the chain m^{14} .

The conveyer-belts m^1 and m^{13} are located 110 so that the lower surface of the belt m^{13} will lie adjacent the upper surface of the belt m^1 , and so that the line of juncture of the two belts is substantially coincident with the plane of the blanks as they are fed forward by the feed belts h^1 . The feed belts h^1 force the blanks between the conveyer belts m^1 and m^{13} ; and, when the latter begin to move, they grip the blanks between them and carry them forward, first to the creaser-presses, then to the slotters, and then to the delivery bands. In order that this may be effected, an intermittent movement is imparted to the lower feed-belt, as stated above. The mechanism for effecting this intermittent movement of the lower conveyer-belt is constructed as follows:

The driving spindle m^8 of the rear sprocket of the lower conveyer-belt, is driven, through the intermediary of a clutch 130

m^{21} (Figs. 12, 15, 32 and 33), by a counter-shaft m^{22} mounted in vertical standards m^{32} . This countershaft carries a bevel wheel m^{23} , which meshes with a bevel pinion m^{24} , carried by the spindle m^6 . The countershaft m^{22} is driven, by means of intermediate gearing m^{25} , from a ratchet shaft m^{26} , also mounted in the standards m^{32} . The ratchet shaft m^{26} has a ratchet connection with a ratchet arm m^{27} , so that it is driven in the direction of the arrow when the ratchet arm is moved toward the left (Figs. 32 and 33), but remains stationary when the ratchet arm is moved toward the right. The effect of the above construction is, that, when the ratchet arm m^{27} is moved toward the left, the shaft m^{26} is rotated, which rotation is communicated, through the countershaft m^{22} , to the sprocket spindle m^8 , provided that the clutch m^{21} is in its operative condition. If the clutch m^{21} should be in its disconnected condition, the countershaft m^{22} will rotate without affecting the sprocket m^8 . When the ratchet arm m^{27} is moved toward the right, the ratchet shaft m^{26} , and the other parts, remain motionless.

The ratchet arm m^{27} is connected, by means of a crank rod m^{28} , with a crank m^{29} carried at the rear end of the longitudinal drive-shaft b^8 , the connection between the crank rod m^{28} and the crank m^{29} being such that the length of the throw of the crank may be increased or diminished, as desired. By adjusting the length of the crank throw, the distance through which the ratchet arm m^{27} moves may be varied, in accordance with the distance through which it is desired that the conveyer belts shall travel. It will be seen from the above that, as the longitudinal drive shaft b^8 rotates, in the direction of the arrow, a swinging movement will be imparted to the ratchet arm m^{27} , first in one direction and then in the other. As has been said, the driving of the lower conveyer belt is effected during the movement of the ratchet arm m^{27} toward the left. During substantially one half of each revolution of the shaft b^8 , therefore, a forward travel of the conveyer-belts is effected; and, during the other half of each revolution of the shaft b^8 , the conveyer belts remain motionless. It will be seen, moreover, that the forward movement of the belts, when it occurs, is slow at first and gradually faster, owing to the fact that when the ratchet arm m^{27} first begins to move in a driving direction, the crank m^{29} will be just passing one of its dead-centers. The effect of the mechanism so far described, therefore, is, that intermittent forward movements, with intervening pauses, are imparted to the conveyer-belts, the forward movements being slow at first and gradually gathering speed until the crank m^{29} has reached a position at right angles to its dead-center, and then decreas-

ing in speed. The creaser-presses and the slotters perform their functions during the pauses between the intermittent forward movements of the conveyer-belts.

The movement of the conveyer-belts will start as soon as the crank m^{29} begins to move the ratchet arm m^{27} to the left, i. e., immediately after the crank passes the position shown in Fig. 32. Without the provision of the brake-applying and clutch-releasing mechanism, to be hereinafter described, the forward travel of the conveyer-belts would cease as soon as the crank m^{29} has turned through 180 degrees from the position shown in Fig. 32. In order, however, to effect the stoppage of the conveyer-belts immediately they have brought a blank in position so that the slotters will form the slots a^5 accurately along the creases a^2 , a clutch-releasing and brake-applying mechanism, actuated by the blank itself, is provided, the effect of which is to stop the travel of the conveyer-belts before they would otherwise be stopped in the manner pointed out above. This mechanism is constructed as follows:

A slide m^{30} is mounted, transversely of the machine, in suitable slide-ways carried by one of the standards m^{32} and a cam-housing m^{31} which forms part of the base of the standard b^{12} . The slide m^{30} is provided with a compression spring m^{33} , the tendency of which is to move the slide toward the right (Figs. 32 and 33). To this slide m^{30} , is connected the lower end of a clutch-actuating lever m^{34} , which is rockably mounted in a bearing m^{35} carried by the standard b^{12} . The upper portion of the clutch-actuating lever m^{34} is forked so as to embrace the movable portion of the clutch m^{21} , this clutch being of such a construction that it will be thrown out when the lower end of the clutch-actuating lever m^{34} is in its right-hand position (Fig. 33), and thrown in when the lower end of the clutch-actuating lever is in its left-hand position (Fig. 32). The movement of the slide m^{30} to one side or the other, therefore, effects the throwing in or out of the clutch m^{21} .

The slide m^{30} carries a cam block m^{36} , which is adapted to be engaged by a roller carried by an arm m^{37} , which extends laterally from a vertical brake shaft m^{38} (Figs. 32 and 35). The brake shaft m^{38} is rockably mounted in bearings carried by the standard b^{12} and by the bed section b^6 , respectively, and has secured thereto, at its upper end, a brake arm m^{39} carrying a brake shoe m^{40} . When the slide m^{30} is moved to the right (looking at the rear end of the machine, as in Fig. 32), the cam block m^{36} rocks the arm m^{37} in a direction to cause the brake shaft m^{38} to force the brake shoe m^{40} against the lower conveyer-belt m^1 . When the slide m^{30} is moved toward the left, the brake shoe is allowed to recede from its position of en-

gagement with the lower conveyer-belt. Thus the effect of moving the slide m^{30} to the right is that the clutch m^{21} is thrown out, and the brake m^{40} is applied; and the effect of moving the slide m^{30} to the left, is that the clutch m^{21} is thrown in and the brake m^{40} is removed.

The slide m^{30} is moved to the left (to throw in the clutch and throw off the brake) 10 immediately before the crank m^{29} reaches the position shown in Fig. 32; so that when the ratchet arm m^{27} starts its driving movement, the belts will begin to travel. The slide is permitted to be moved to the right, 15 by its spring m^{33} (thereby to throw out the clutch and throw on the brake, and thus stop the conveyer-belts) by a mechanism which is tripped by the blank itself, just as the latter is brought into the proper position 20 beneath the slotters.

To these ends, the longitudinal drive shaft b^8 has secured thereto a cam m^{41} . The cam m^{41} has an inclined surface m^{42} , extending through substantially a quarter of a circle, 25 and has a sustaining surface m^{43} extending through about three-eighths of a circle. The remainder of the circle is open. Coöperating with the cam m^{41} , is a roller carried by a cam-lever m^{44} , which is secured to a shaft m^{45} rockably mounted in bearings carried by the housing m^{31} . An arm m^{46} is also secured to the shaft m^{45} , and is connected, at its end, with the slide m^{30} . The effect is, that, as the cam m^{41} causes the cam-lever m^{44} to be moved 30 to the left (owing to the action of the inclined cam-surface m^{42}), just before the crank m^{29} reaches the position shown in Fig. 32, the slide m^{30} will be moved to the left, thus throwing in the clutch and throwing off the brake before the ratchet arm m^{27} begins its driving movement. The sustaining surface m^{43} of the cam holds the slide m^{30} in this position, for a time.

The length of the sustaining surface m^{43} 45 of the cam is less than a semi-circle;—i. e., the surface m^{43} is not long enough to sustain the cam lever m^{44} during the entire half revolution of the shaft b^8 in which the ratchet arm m^{27} is performing its driving movement. During the last part of the driving movement of the ratchet arm m^{27} , therefore, the open part of the cam m^{41} will be opposite the end of the cam-lever m^{44} . When the open part of the cam m^{41} 50 has thus come opposite the end of the cam-lever m^{44} , the slide m^{30} will be prevented from moving to the right, under the influence of its spring m^{33} , by a vertical stop-lever m^{47} , which is secured to the shaft m^{45} . At the time when the end of the sustaining surface m^{43} of the cam passes away 55 from the end of the cam-lever m^{44} , the top of the stop-lever m^{47} will be engaged by a stop m^{48} . This stop prevents the stop-lever m^{47} from swinging to the left, and

thus prevents the slide m^{30} from being moved to the right under the action of its spring m^{33} . When, however, the stop m^{48} is removed from the path of the stop-lever m^{47} , the latter is left free to swing to the left; and, the open part of the cam being opposite to the end of the cam-lever m^{44} , there is nothing to prevent the slide m^{30} from being moved to the right. The slide m^{30} , therefore, snaps to the right, under the action of its spring m^{33} , thus throwing out the clutch and throwing on the brake, thereby causing the stoppage of the conveyer-belts. The removal of the stop m^{48} from the path of the stop-lever m^{47} is effected by the blank itself, by mechanism now to be described.

The stop m^{48} is mounted at the rear end of a longitudinally disposed rock-beam m^{49} (Figs. 12, 15 and 36-38), which is pivoted to a bracket m^{50} secured to the standard b^{13} . The bracket m^{50} lies close at one side of the lower conveyer-belt m^1 , and somewhat below the same; and it carries, at its front end, a trigger frame m^{51} . The trigger frame m^{51} is pivoted to the bracket m^{50} , and carries, at its rear end, a roller m^{52} , which is adapted to ride upon the top surface of the front end of the rock-beam m^{49} , so that, when the trigger frame is rocked downwardly, the rear end of the rock-beam m^{49} will be raised, against the action of a spring m^{58} , to remove the stop m^{48} from the path of the stop arm m^{47} . The top part of the trigger frame m^{51} is formed with a pair 90 of split lugs m^{53} , between which is mounted a thumb nut m^{54} , through which passes a threaded pin m^{55} , upon the front end of which is secured a trigger m^{56} . The parts are so proportioned that the tip of the trigger m^{56} projects slightly above the plane of the lower conveyer-belt m^1 , into the path of the blanks,—so that, when a blank strikes the trigger m^{56} , the trigger frame m^{51} will be rocked downward, thus removing the stop m^{48} from the path of the stop arm m^{47} . Fine adjustments of the position of the trigger m^{56} may be made by means of the thumb nut m^{54} , the trigger being secured in its adjusted position by drawing the split lugs 95 m^{53} together by means of a cap screw m^{57} .

With the above description of the several mechanical devices employed, the operation of the conveyer-belt driving mechanism is as follows: When the parts are in the position shown in Figs. 12, 15 and 33, the creaser-presses and the slotters are at the middle of their operation, two blanks being held by the conveyer-belt stationary beneath the creaser-presses and the slotters, respectively. As will be seen, the ratchet arm m^{27} is at the center of its idle movement. The conveyer-belts are stationary, the slide m^{30} being in its right-hand position, with the clutch out and the brake ap- 100 105 110 115 120 125 130

- plied. The brake being operated upon by the slotters, is a trifle in advance of its position, with respect to the clutch-tripping mechanism, shown in Fig. 36; however, the 5 rock-beam m^{49} , having previously been depressed at its front end by the engagement of the blank with the trigger m^{56} , will be in the position indicated in dotted lines in Fig. 36 and shown in full lines in Fig. 37. 10 The cam m^{41} is in a position turned about 90 degrees backward from the position shown in Fig. 32.

In Fig. 32 the shaft b^8 is shown as having rotated through about 90 degrees, in 15 the direction of the arrows, from the position shown in Fig. 33. The ratchet arm m^{27} has reached the limit of its idle movement and is about to begin its driving movement. During the revolution of the shaft 20 b^8 from the position shown in Fig. 33 to that shown in Fig. 32, the inclined surface m^{42} of the cam m^{41} will have moved the cam-lever m^{44} to the left, whereby the stop-lever m^{47} will have been moved to the right, 25 ready to be engaged by the stop m^{48} , when the rear end of the rock-beam is subsequently permitted to fall. The blank will not yet have moved; and the rock-beam m^{49} will consequently still occupy the position 30 shown in dotted lines in Fig. 36. The movement of the cam-lever m^{44} to the left will also have caused the slide m^{30} to be moved to the left by the arm m^{46} , whereby the brake m^{40} will have been removed and 35 the clutch m^{21} thrown in, ready to drive the sprocket m^5 of the lower conveyer-belt when the ratchet-arm begins its driving movement.

As the shaft b^8 continues its rotation, in 40 the direction of the arrow, from the position shown in Fig. 32, the ratchet-arm m^{27} will begin its driving movement, and will cause the rear sprocket m^5 to commence to rotate, and the conveyer belts to commence to move 45 forward. This forward movement will be slow at first (owing to the fact that the crank m^{29} is just passing its dead-center position), but will gradually increase, until it reaches a maximum speed when the crank m^{29} is in a 50 position at right angles to that shown in Fig. 32. During the first part of the movement of the crank m^{29} from the position shown in Fig. 32, the clutch and brake actuating slide m^{30} will be kept in its left-hand position by the cam-lever m^{44} co-operating with the sustaining surface m^{43} of the cam m^{41} . During the time, the blank is being conveyed forward to the delivery bands, and the trigger and rock-beam are in the position shown in Fig. 37, the rear end of the rock-beam being prevented from dropping by reason of the engagement of the trigger m^{56} with the under side of the moving blank. 60 The blank, however, will have passed away 65 from above the trigger m^{56} , before the sus-

taining surface m^{43} of the cam has passed away from the end of the cam-lever m^{44} . As soon as the blank has thus passed away from above the trigger m^{56} , the spring m^{58} will return the trigger and the rock-beam to 70 the positions shown in full lines in Fig. 36, thus moving the stop m^{48} into the path of the stop-lever m^{47} . Thus, subsequently, when the open portion of the cam m^{41} comes opposite the end of the cam-lever m^{44} , the 75 slide m^{30} will be prevented from moving to the right (and thus throwing out the clutch and throwing on the brake) by the engagement of the stop-arm m^{47} with the stop m^{48} .

By this time, the next succeeding blank 80 (which has just been operated upon by the creaser-presses) will be approaching the trigger m^{56} (Fig. 36). When this blank strikes the trigger m^{56} , it will force the latter downward into the position shown in 85 Fig. 37, the stop m^{48} being thus removed from the path of the stop-arm m^{47} . The removal of the stop m^{48} from the path of the stop-arm m^{47} permits the slide m^{30} to snap to the right, and thus throw out the clutch and 90 throw on the brake. The engagement of the advancing blank with the trigger m^{56} thus causes the conveyer-belts to be stopped. At the time when the conveyer-belts are 95 stopped as described above, they will have but little momentum, owing to the fact that the crank m^{29} will be approaching the dead center opposite to that shown in Fig. 32, and the conveyer-belt will therefore already have been almost brought to a standstill. 100 The parts of the machine are so disposed that the blank will have just reached its correct position beneath the slotters when the conveyer-belts are stopped, by the engagement of the blank with the trigger m^{56} , as 105 described above. During the remainder of the revolution of the shaft b^8 , until it reaches again the position shown in Fig. 32, the conveyer-belts will remain stationary, the creaser-presses and the slotters performing their operations upon the blanks at this time.

Creaser-presses.

The creaser-presses are carried by the center frames b^{15} and b^{16} , which extend longitudinally of the machine one on each side of the conveyer-belts. The creaser-presses are mounted on each side of the machine, and are duplicates, so that a description of one 115 of them will suffice. Each of the center frames b^{15} and b^{16} carries, at its outer side, three bearings o^1 (Figs. 14 and 15), in which is mounted a rock-shaft o^2 , adapted to have a rocking movement imparted thereto by eccentrics connected with the longitudinal drive-shaft, as will be hereinafter described. The rock-shaft o^2 has secured thereto a pair of inwardly-extending arms o^3 , to the inner ends of which is bolted a 120

125 130

longitudinally-extending creaser-beam σ^4 . The length of the arms σ^3 is such that the creaser-beam σ^4 will lie parallel with, and somewhat within, the edge of the table h^{15} . 5 One of these tables, it will be remembered, extends beneath each of the creaser-presses. The beam σ^4 has secured thereto a long reversible female die σ^5 (Fig. 40). This die is held in position by a plurality of cap 10 screws σ^6 passing through vertically-elongated slots σ^7 formed therein and entering the creaser-beam σ^4 . Vertically disposed set screws σ^8 are provided, for effecting fine 15 adjustments of the die, these set screws engaging a bearing strip σ^9 , placed in the upper groove of the die. By loosening the cap screws σ^6 and manipulating the set screws σ^8 , a very delicate vertical adjustment of the die σ^5 may be made, the set screws σ^6 being 20 subsequently tightened to hold the die in its adjusted position. By entirely removing the set screws σ^6 , the die σ^5 may be reversed, for producing a more narrow crease. Secured to each of the center frames, beneath 25 the creaser-beams σ^4 , is a longitudinally-extending stationary beam σ^{10} , in the top edge of which is formed a recess for receiving a male die σ^{11} , which cooperates with the female die σ^5 . This die, like the die σ^5 , is reversible. It will be seen that, when the 30 creaser-beams descend upon the blank, which will be held, by the conveyer-belts, stationary above the dies σ^{11} , the longitudinal creases σ^4 will be formed in the blank. 35 At each end of the center frames, the rock-shafts σ^2 are provided with downwardly extending cranks σ^{12} (Figs. 17 and 33), the lower ends of which are connected, by means of pivoted clamps σ^{16} , to the outer ends of 40 eccentric rods σ^{13} . The eccentric rods σ^{13} are connected with the straps σ^{14} of eccentrics σ^{15} carried by the longitudinal drive-shaft b^8 . The eccentrics are so disposed that the rock-shafts σ^2 will be rocked simultaneously, so as to cause the creaser-beams σ^4 , with their dies σ^5 , to descend simultaneously upon the blank which is beneath them. The rock-shafts σ^2 are provided with counterweights σ^{20} which counterbalance the 50 weight of the creaser-beams, slotter-arms, etc., and thus permit a smooth and regular driving of the machine. 55 The blank is carried along the tables h^{15} , by the feed belts h^1 , with its edges in contact with the guides h^{16} , and is stopped as soon as it reaches the conveyer-belts, m^{13} . When the conveyer-belts begin to rotate, they grasp the blank and move it forward along the tables h^{15} , and with its edge still 60 engaging the gages h^{16} , far enough to bring it beneath the dies whereupon the conveyer-belts stop again. As soon as the conveyer belts have stopped, the creaser-beams σ^4 move down, to impress the longitudinal creases σ^4 in the blank. 65

The eccentrics σ^{15} are so disposed that they reach the centers of their up and down movements, substantially at the time when the conveyer belts are starting and stopping, respectively. This will be readily understood by reference to Figs. 17 and 32, the position of the shaft b^8 being the same in both these figures. In these figures, the conveyer belts are shown as being just about to start to travel, the creaser-beams having moved 70 through one-half of their upward travel. During the next half revolution of the shaft b^8 , in which the conveyer-belts move forward, the creaser-beams will move upward and then back again to the same positions as 80 those shown in Fig. 17. During the following half revolution of the shaft b^8 , in which the conveyer-belt is stationary, the creaser-beams move down to their lowermost position, thus impressing the longitudinal 85 creases σ^4 in the blank, and return to the position shown in Fig. 17. While the creaser-presses are forming the longitudinal creases σ^4 , the slotters are cutting out the slots σ^5 and the corners σ^6 from the preceding blank. 90

Slotters.

The slotters are arranged in two sets of four, one set being mounted on the center frame b^{15} , at one side of the machine, and 95 the other set being mounted on the center frame b^{16} , at the other side of the machine. Each set consists of one corner-slotter and three line-slotters. The corner-slotters cut out the corners σ^6 from the blank, and the 100 line-slotters punch out the three slots σ^5 at each side of the blank.

The corner-slotters on each side of the machine are duplicates, and a description of one of them, therefore, will suffice. Each 105 corner-slotter comprises a slotter-arm p^1 (Figs. 15 and 41-45) carried by one of the rock-shafts σ^2 which operate the creaser-presses. The slotter-arm is feathered to the rock-shaft σ^2 by means of a key p^{19} which 110 engages a keyway extending longitudinally of the rock-shaft, whereby the slotter-arm may be moved longitudinally on the rock-shaft without changing the angular position with respect thereto. Clamping bolts 115 p^6 are provided for securing the slotter-arm against such longitudinal movement, except when desired. The slotter-arm has secured to the side thereof facing the rear end of the machine, a side knife p^2 . The knife p^2 is 120 held in place by means of cap screws p^3 which pass through vertically-elongated slots p^4 formed in the knife. Adjusting screws p^5 are provided, engaging the upper part of the knife p^2 . By loosening the cap 125 screws p^3 and manipulating the adjusting screws p^5 , fine vertical adjustments of the knife may be effected. An end knife p^7 is secured to the inner end of the arm p^1 , by means of cap screws p^8 passing through 130

slots p^8 in the knife. The end knife p^7 is engaged by adjusting screws p^{10} in a manner similar to that in which the side knife p^2 is engaged by the adjusting screws p^5 . The knives p^2 and p^7 are formed so as to make a miter joint at their adjacent ends, as shown in Fig. 45, whereby they present a continuous angular cutting edge.

A die-supporting arm p^{11} , which consists of two members, secured together by spacing bolts p^{12} , so as to embrace loosely the slotted-arm p^1 between them, is also carried by the rock-shaft o^2 . The arm p^{11} is not feathered to the rock-shaft o^2 , and its inner end rests upon the center frame, so that the die-supporting arm will remain stationary during the rocking movements of the rock-shaft o^2 . The die-supporting arm p^{11} has secured thereto a side die p^{13} adapted to cooperate with the side knife p^2 of the slotted-arm p^1 . The side die is held in place by means of cap screws p^{14} passing through elongated slots therein, adjusting screws p^{15} being provided for effecting adjustments of the die toward and away from the knife p^2 . The die-supporting arm p^{11} also has secured thereto, by means of side clamps p^{20} , an end die p^{16} adapted for cooperation with the knife p^7 . The end die p^{16} is adapted to be adjusted endwise by means of cap screws p^{21} . A stripper p^{17} is provided, for preventing the blank from rising with the slotted-arm.

The corner-slotter, with its knives p^2 and p^7 , is disposed so that the knife p^7 is in a line with the dies o^6 of the creaser-presses, and so that the knife p^2 will be in a line with the rearmost transverse crease a^2 of the blank, when the blank has been stopped beneath the slotters. When the slotted-arms p^1 of the two corner-slotters descend, they, in conjunction with the cooperating dies, will cut away the corners a^6 from the blank.

The six line-slotters, three on each side of the machine, are duplicates, and a description of one of them, therefore, will suffice. Each line-sлотter (Figs. 15 and 46-50) comprises a slotted-arm r^1 , which is feathered upon one of the rock shafts o^2 and secured by bolts r^2 , in a similar manner to that in which the slotted-arms p^1 of the corner-slotters are mounted. The slotted-arm r^1 has secured thereto a blade r^3 . The blade r^3 is held in place by means of cap screws r^4 passing through slots therein, the slots being sufficiently large to admit of reversal, and longitudinal adjustment of the blade. Adjusting screws r^5 , the heads of which bear against the end of the blade r^3 , are provided for effecting lengthwise end adjustments of the blade.

Loosely mounted on the rock-shaft o^2 , in a manner similar to that in which the die-supporting arms p^{11} of the corner-slotters

are mounted, and with its inner end resting upon the center frame, is a die-supporting arm r^6 . The die-supporting arm consists of two parts, secured together by means of spacing bolts r^7 so as to embrace loosely the slotted-arm r^1 between them, so that the die-supporting arm r^6 will remain stationary during the rocking movements of the slotted-arm r^1 . The die-supporting arm carries a pair of side dies r^8 , disposed one on each side of the blade r^3 , so that the latter will pass down between them during the rocking movement of the slotted arm. The side dies are held in place by means of set screws r^9 passing through horizontally elongated slots r^{10} therein. Adjusting screws r^{11} , the heads of which are adapted to engage the outer edges of the side dies r^8 , are provided, for effecting fine adjustments of these dies toward and away from the blade r^3 . Besides the side dies r^8 , an end die r^{12} (Fig. 31) is provided to cooperate with the end of the blade r^3 , thus effecting the severing of the strip which will be punched out from the blank when the blade r^3 passes down between the dies r^8 . The end die r^{12} is secured to the die-supporting arm r^6 in a manner similar to that employed for mounting the end dies p^{16} of the corner-slotters. Strippers r^{13} are provided, one on each side of the slotted-arm r^1 , to prevent the blank from rising with the slotted-arm, when the latter ascends after the slotting operation.

It will be seen that, in order that the line-slotters may form the slots a^5 in the blank at the proper positions, these slotters must be placed so that their blades r^3 will be in position immediately above the transverse creases a^2 , when the blank is stopped beneath the slotters.

To the above end, the first pair of line-slotters are placed with their blades at a distance behind the trigger m^{56} equal to the distance between the front edge a^1 of the blank and the first transverse crease a^2 , i. e. a distance equal to the width of the first panel a^0 ; the second pair of line slotters are placed with their knives at a distance behind the blades of the first pair equal to the width of the first panel a^0 ; the third pair of slotters are placed with their blades at a distance behind the blades of the second pair of slotters equal to the width of the second panel a^0 ; and the corner-slotters are placed with their knives at a distance behind the blades of the third pair of line-slotters equal to the width of the second panel a^0 . With the line-slotters and corner-slotters arranged in this manner, the slots a^5 must necessarily be punched out, and the corners a^6 must be cut away, in the proper position with respect to the transverse creases a^2 .

The tables h^{15} stop short of the slotters, and, to prevent the edges of the blanks from

sagging downward between the die-supporting arms, adjustable supporting bars s^1 are provided (Figs. 15, 52 and 53). These supporting-bars are interposed between the die-supporting arms of the slotters, with their top edges flush with the top surfaces of the die-supporting arms. The supporting-bars have a tongue and groove connection, and are secured together by means of bolts s^2 passing through elongated slots s^3 in the bars. By loosening the bolts, the length of the bars may be adjusted in accordance with the distance between the supporting-arms.

- 15 When it is desired to produce a box-blank in which the distances between the transverse creases a^2 will be different from those between the transverse creases of the blank theretofore produced by the machine, it will 20 be necessary, of course, to adjust the slotters lengthwise with respect to each other and with respect to the trigger m^{58} . To this end a screw-threaded spindle t^1 is mounted in suitable bearings t^2 (Figs. 7-8, 14-15, 25 44 and 51) upon each of the center frames b^{15} , b^{16} . The threaded spindles t^1 pass freely through the die-supporting arms r^6 and p^{11} of the line-slotters and corner-slotters respectively; and are provided, at their 30 rear ends, with worm pinions t^3 . With the worm pinions t^3 engage worms carried by spindles t^4 rotatably mounted at the ends of the center frames b^{15} , b^{16} . The spindles t^4 are provided at their outer ends with hand- 35 wheels t^5 , by means of which the spindles may be rotated, thus causing the threaded shafts t^1 to revolve.

As has been said, the threaded shafts t^1 pass freely through the die-supporting arms 40 of the slotters. The die-supporting arms of the slotters are, however, provided with means whereby they may be caused to make threaded connection with the threaded shafts t^1 , when it is desired to adjust them longitudinally of the machine. This means for effecting a threaded connection between the die-supporting arms and the threaded shafts t^1 is the same for the line-slotters as for the corner-slotters, and it will therefore be sufficient 45 to describe it in connection with one of the corner slotters.

Referring now particularly, therefore, to Figs. 44 and 51, which are a rear view of a corner slotter, and a side view of the same 50 with one of the parts of the die-supporting arm p^{11} removed, respectively, a hand-lever t^6 is pivoted, at t^7 , to the die-supporting arm p^{11} . The hand-lever t^6 has pivotally connected therewith, at its upper end, a half-nut t^8 , which is mounted to slide horizontally in guides t^9 carried by the arm p^{11} . When the lower end of the lever t^6 is moved to the left from the position shown in Fig. 51, the half-nut t^8 is moved into mesh with 55 the threads of the shaft t^1 , whereby a thread-

ed connection is established between the slotted and the shaft t^1 . When the lever t^6 is moved to the right, into the position shown in Fig. 51, the half-nut t^8 is removed from connection with the threaded shaft t^1 , and any revolution of the latter which may take place will, therefore, not affect the slotted. A spring t^{10} is provided, for holding the half-nut t^8 in threaded engagement with the shaft t^1 , when it has been permitted to move into such engagement. The hand-lever t^6 carries a spring-actuated latch-lever t^{11} , which is pivoted thereto, and which carries, at its upper end, a latch pin t^{12} . The latch pin t^{12} passes through the hand-lever t^6 , and is adapted to enter a hole t^{13} in the arm p^{11} , when the hand-lever t^6 is in the position shown in Fig. 51. The latch pin serves to maintain the lever t^6 in the position in which the half-nut t^8 is out of engagement with the threaded shaft t^1 (Fig. 51). However, when it is desired to cause the half-nut t^8 to move into engagement with the threaded shaft t^1 , this may be effected by operating the latch lever t^{11} to remove the latch pin t^{12} , whereupon the spring t^{10} will cause the lever t^6 to swing about its pivot and the half-nut t^8 to move into engagement with the threaded shaft.

The use of the hand-lever t^6 and half-nuts t^8 in adjusting the slotters to their proper positions is as follows,—supposing, for instance, it is desired to change the slotters from the position shown in Fig. 15, to another position, to permit them to form the slots in a blank of a different nature: The bolts p^6 of the slotted-arms of the corner-slotters, and the bolts r^2 of the line-slotters are first loosened, whereupon these slotted-arms may be moved longitudinally of the rock-shafts o^2 , carrying with them the die-supporting arms, which, it will be remembered, are loose upon the rock-shafts. At this time, the hand-levers t^6 are in the positions in which the half-nuts t^8 are out of engagement with the threaded shafts t^1 . The first pair of line-slotters are preferably adjusted first; and, to this end, the latch-levers t^{11} of the hand-levers t^6 of the first pair of line-slotters are operated, to permit the half-nuts to be moved by the springs t^{10} into threaded engagement with the threaded shafts t^1 . The shafts t^1 are now rotated, by means of the hand-wheels t^5 , the front pair of line-slotters being thus brought into their adjusted position with relation to the trigger m^{58} . The remaining slotters remain stationary owing to the fact that they have no threaded engagement with the shafts t^1 . When this adjustment of the front pair of line-slotters has been effected, the bolts r^2 are tightened, thus securing the front pair of line-slotters in their adjusted position upon the rock-shafts o^2 . The hand-levers t^6 of the front pair of line-slotters are then moved 110 115 120 125 130

back into the position shown in Fig. 51, in which position they are locked by the latch pin t^{12} . The front pair of line-slotters having been thus brought to the proper position, the other slotters are adjusted to their proper positions in the same manner.

Lateral adjustment of center frames.

The means for adjusting the longitudinal distance between the slotters for different kinds of blank has been described above. When the longitudinal distance between the slotters is changed, it will usually be necessary also to change the lateral distance between the center frames; since when the distances between the transverse creases a^2 , and consequently the distances between the slots a^6 , is varied, it will usually be necessary to vary the position of the longitudinal creases a^4 . To this end, the center frames are slidably mounted, as has been stated above, on transverse slide-ways b^{14} . They are normally clamped, however, against lateral movement on the slide-ways, by means of clamps w^1 , which are secured to the center frames b^{15} and b^{16} , at the ends of the same, so as to engage beneath the adjacent slide-ways b^{14} (Figs. 6 and 8). A pair of transverse threaded shafts w^2 , one at each end of the frames b^{15} , b^{16} , extend across the machine, through nuts w^3 carried by the center frames. The threads of the shaft w^2 run in opposite directions at the ends of the same, so that the center frames will be caused to approach toward, or recede from, each other, according to the direction in which the shafts w^2 are rotated. Each of the shafts w^2 has secured thereto, to one side of the center thereto, to one side of the center thereof, a worm wheel w^4 . Worms w^5 , carried by a longitudinal shaft w^6 engage the worm wheels m^4 , so that rotation of the shaft w^6 is transmitted to the threaded shafts w^2 . The worm shaft w^6 carries a bevel gear w^7 which meshes with a corresponding bevel pinion w^8 carried by the inner end of a stub-shaft w^9 which extends out to one side of the machine (Figs. 7 and 14). The stub-shaft w^9 carries a pulley w^{10} , adapted to receive a belt connected with any suitable source of power. The stub-shaft w^9 also carries a sprocket w^{11} around which passes a chain w^{12} . The chain w^{12} also passes around a sprocket w^{13} mounted in the upper end of a standard w^{14} , and adapted to be turned by means of a hand crank w^{15} .

When it is desired to move the center frames b^{15} , b^{16} toward or away from each other, in order to adjust these frames for the production of another kind of blank, the clamps w^1 are first loosened, and power is transmitted to the pulley w^{10} of the stub-shaft w^9 so as to turn the stub-shaft w^9 , and consequently the worm shaft w^6 in the proper direction for the desired movement of the

center frames. As soon as the center frames have reached approximately the desired position, power is cut off from the pulley w^{10} , and the final, accurate, adjustment of the center frame made by operating the crank w^{15} .

When the lateral adjustment of the center frames is made, it is necessary that the proper positioning of the cranks o^{12} , which effect the rocking of the shaft o^2 with respect to the eccentrics o^{15} , shall be maintained. To this end, a locking crank w^{16} (Figs. 10 and 17) is mounted on the longitudinal drive-shaft b^8 , adjacent the front bearing standard b^{12} for the conveyer belts. The locking crank w^{16} has an indicating finger w^{17} at its outer end; and the crank is so disposed that this finger will come opposite an index w^{18} on the standard b^{12} , when the shaft b^8 is in the proper position for the center frames to be adjusted. The locking crank w^{16} is provided with a hole w^{19} , through which a removable dowel-pin w^{20} (Fig. 10) may be inserted into a corresponding hole formed in the standard b^{12} , when the indicating finger w^{17} is opposite the index w^{18} . The dowel pin w^{20} is provided with a handle w^{21} , to facilitate its insertion and withdrawal. The cranks o^{12} carry threaded dowel-pins w^{22} , adapted to be operated by hand-wheels w^{23} . The dowel-pins w^{22} are adapted to enter corresponding holes in the center frames b^{15} , b^{16} , when the shaft b^8 is in the position in which the indicating finger w^{17} registers with the index w^{18} .

When it is desired to adjust the center frames laterally, the shaft b^8 is rotated until the indicating finger w^{17} registers with the index w^{18} , and the dowel-pin w^{20} is then thrust through the hole w^{19} of the locking crank w^{16} into the corresponding hole of the standard b^{12} . The threaded dowel-pins w^{22} are screwed in, by means of the hand-wheels w^{23} so as to enter the holes in the center frames. The shaft b^8 and the cranks o^{12} are thus firmly locked against movement. The clamps w^{16} which connect the cranks o^{12} with the eccentric rods o^{13} are then loosened, whereupon the adjustment of the center frames by means of the threaded shafts w^2 , as described above, can be made, the parts being held in their proper relation during the adjustment of the center frames. After the adjustment has been made, the clamps w^{16} are tightened again, the dowel-pins w^{22} retracted from the holes in the center frames, and the dowel-pin w^{20} is entirely removed.

Delivery bands.

The finished blanks are delivered by the conveyer belts m^1 , m^{13} onto delivery bands x^1 at the rear end of the machine (Figs. 12 and 33). These bands pass around front pulleys x^2 mounted on a transverse spindle x^3 which is rotatably mounted in hangers

x' carried by the rear supporting-arch *b*¹¹. The rear pulleys *x*⁵ for the delivery bands are secured to a transverse spindle *x*⁶ mounted in suitable brackets *x*⁷, one of which is secured to a standard *x*⁹, and the other of which is secured to the standard *m*³² which supports the ratchet shaft. An inclined shaft *x*⁸ having bevel pinion connection with the longitudinal drive-shaft *b*⁸ and with the transverse spindle *x*³, transmits power to the delivery bands. The finished blanks may be delivered, by means of the bands *x*¹, onto a suitable table, or to a chute or the like, as desired.

15

Operation.

In the making-up of the machine, preparatory to the production of a quantity of blanks, the lateral guide *c*³¹ is first adjusted to the proper position for the width of blank being used. The dies of the creaser-reels *f*¹, *f*² are then set so as to produce the transverse creases *a*², at the correct distances apart. The rotary trimmers are then adjusted transversely upon the trimmer-shafts *g*¹ and *g*² so as to trim the edges *a*³ of the blank to give the requisite width. The center frames *b*¹⁵, *b*¹⁶ are then adjusted so as to bring the dies of the creaser-presses in the correct position to produce the longitudinal creases *a*⁴ at the proper distance from the side edges *a*³. Lastly, the corner-slotters and line-slotters are adjusted with relation to each other, and with relation to the trigger *m*⁵⁰, so as to form the slots along the transverse creases *a*². When these adjustments have been made, the machine will continuously produce blanks of the required dimensions.

40 The various positions of the blanks in the machine, during successive periods in a cycle of the machine, will be best understood by reference to Figs. 56-59. In Fig. 56 the parts of the machine are diagrammatically shown in the positions which they occupy when a blank is just about to be fed into the machine. The creaser-reels *f*¹, *f*² are in the position shown in Fig. 5; and the conveyer belts, creaser-presses, and slotters are in the positions which they occupy when the conveyer-belts are about to start their movement, *i. e.*, in the positions indicated in Fig. 32. With the parts in these positions, the slotters are at the middle of their upward movement, and a blank A, which has just been slotted, is immediately beneath them. The dies of the creaser-presses are also at the middle of their upward movement; and a blank B, which has just had the longitudinal creases impressed therein, is immediately beneath them. A blank C is first forced, by the feed belts, against the entrance between the conveyer-belts. A blank D is in position upon the feed table, with its front edge against the spacing-stop. As

the machine moves forward from the position shown in Fig. 56, the conveyer-belts begin to move, the blank A being thereby moved toward delivery, the blank B being moved toward the slotters, and the blank C being moved toward the creaser-presses. At the same time the spacing-stop drops and the feeding of the blank D to the creaser-reels is commenced. In Fig. 57, the creaser-reels have turned through one-half a revolution, and the longitudinal drive-shaft has moved through one-quarter revolution (it being remembered that the creaser-reels have one operative revolution and one idle revolution for each revolution of the longitudinal drive-shaft). In Fig. 57, therefore, the conveyer-belts have moved through substantially one-half their travel; and, consequently, the blank A has been moved half way toward delivery, the blank B has been moved half-way toward the slotters, and the blank C has been moved half-way toward the creaser-presses, the slotters and the creaser-dies being in their extreme uppermost position. The blank D has partly passed through the creaser-reels. In Fig. 58 the creaser-reels have turned through another half-revolution, and the longitudinal drive-shaft through another quarter of a revolution. The blank A has passed on to the delivery band. The blank B is in position beneath the slotters, having just actuated the clutch-releasing and brake-applying trigger, thereby stopping the conveyer-belts. The blank C is in position beneath the creaser-presses. And the blank D has passed through the creaser-reels and is just entering upon the feed belts. The creaser-beams and slotters have effected one-half their downward movement. In Fig. 59, the creaser-reels have moved through the first half of their second, idle, revolution, and the longitudinal drive-shaft has moved through another quarter revolution, the conveyer-belts being stationary, and the creaser-dies and slotters being at their extreme lowermost positions. The blanks B and C are just being slotted and creased respectively. The blank D is upon the feed belts, and approaching the entrance between the conveyer-belts. And another blank, E, has been manually placed upon the feed table, with its front edge against the spacing-stop. The next half revolution of the creaser-reels will complete the cycle of the machine, and bring the parts back to the positions shown in Fig. 56, with the blanks B, C, D and E occupying the positions previously occupied by the blanks A, B, C and D, respectively. In this manner a blank is received at one end of the machine, and a finished blank is delivered at the other end of the machine, at each cycle of the machine.

Adjustments of the various parts of the

- machine may be made in the manners indicated in the descriptions of the various mechanisms, as well as in the ordinary manners known to the art. Provision is made for 5 stopping the machine suddenly, in case of necessity. To this end, a brake y^1 (Figs. 9, 13, and 16) is provided. This brake is mounted on a rock-shaft y^2 , which also has secured thereto an upwardly-extending arm y^3 . 10 The arm y^3 is connected, by means of a link y^4 , with an arm y^5 , which extends upwardly from the hub of a foot-lever y^6 , which is loosely mounted on the transverse shaft e^3 , a spring being provided for normally holding the brake in its off position. The brake engages one of a pair of hand-wheels y^7 , which are secured to each end of the main shaft f^3 , to permit the same to be turned by hand when required, during the adjustments, etc., of the machine. It will be seen that if power be cut off from the driving-pulley of the main shaft f^3 , and the brake lever y^6 be depressed, the machine will immediately be brought to a standstill. 15 Having thus described my invention, what I claim as new and desire to secure by Letters Patent, is:
1. In a machine for creasing blanks, the combination with a rotary device for forming transverse creases in the blanks, with a reciprocating device for forming longitudinal creases in the blanks, and continuously progressing intermittently operated means for conveying the blanks from said rotary creasing device to a position of rest beneath said reciprocating creasing device, and subsequently removing them. 20
  2. In a machine for creasing blanks, in combination, a rotary device for forming transverse creases in the blanks, a device for trimming the longitudinal edges of the blanks, a reciprocating device for forming longitudinal creases in the blanks, and continuously progressing intermittently operated means for conveying the blanks from said rotary creasing device to a position of rest in operative relation with said reciprocating creasing device, and subsequently removing the blanks. 25
  3. In a machine for creasing and slotting blanks, in combination, a rotary creasing device for forming transverse creases in the blanks, a reciprocating device for forming longitudinal creases in the blanks, a slotting device for forming slots in the blanks along the transverse creases, and means for conveying the blanks into operative relation with each of said devices in succession. 30
  4. In a machine for creasing and slotting blanks, in combination, a rotary creasing device for forming transverse creases in the blanks, a device for trimming the longitudinal edges of the blanks, a reciprocating device for forming longitudinal creases in the blanks, a slotting device for forming slots in the blanks, and means for 35

slots in the blanks along the transverse creases, and means for conveying the blanks into operative relation with each of said devices in succession.

5. In a machine for creasing and slotting blanks, in combination, a rotary creasing device for forming transverse creases in the blanks, a reciprocating device for forming longitudinal creases in the blanks, a slotting device for forming slots in the blanks along the transverse creases, means for conveying the blanks from said rotary creasing device to a position of rest in operative relation with said reciprocating creasing device, and means for conveying the blanks from said reciprocating creasing device to said slotting device. 70

6. In a machine for creasing and slotting blanks, in combination, a rotary creasing device for forming transverse creases in the blanks, a reciprocating device for forming longitudinal creases in the blanks, a reciprocating slotting device for forming slots in the blanks along the transverse creases, means for conveying the blanks from said rotary creasing device to a position of rest in operative relation with said reciprocating creasing device, and means for conveying the blanks from said reciprocating creasing device to a position of rest in operative relation with said slotting device. 80

7. In a machine for creasing and slotting blanks, in combination, a rotary creasing device for forming transverse creases in the blanks, a device for trimming the longitudinal edges of the blanks, a reciprocating creasing device for forming longitudinal creases in the blanks, a reciprocating slotting device for forming slots in the blanks along the transverse creases, and means for conveying the blanks into operative relation with each of said devices in succession. 100

8. In a machine for creasing and slotting blanks, in combination, a rotary creasing device for forming transverse creases in the blanks, a reciprocating slotting device for forming slots in the blanks along the transverse creases, and means for conveying the blanks from said creasing device to said slotting device. 110

9. In a machine for creasing and slotting blanks, in combination, a rotary creasing device for forming transverse creases in the blanks, a reciprocating slotting device for forming slots in the blanks along the transverse creases, and means for conveying the blanks from said rotary creasing device to a position of rest in operative relation with said slotting device, and subsequently removing them. 120

10. In a machine for creasing and slotting blanks, the combination of a rotary creasing device for forming transverse creases in the blanks, a reciprocating slotting device for forming slots in the blanks, and means for 130

conveying the blanks from one of such devices to such a position with relation to the other that the creases and slots will coincide.

11. In a machine for creasing and slotting blanks, a rotary creasing device for forming transverse creases in the blanks, a reciprocating slotting device for forming transverse slots in the blanks, and means for conveying the blanks from said rotary creasing device to rest at such a position with relation to said slotting device that said slots will coincide with said creases.

12. In a machine for creasing and slotting blanks, a rotary creasing device for forming transverse creases in the blanks, a reciprocating slotting device for forming transverse slots in the blanks, a traveling conveyer for conveying the blanks from said rotary creasing device to said reciprocating slotting device, means for stopping said conveyer when each blank has been brought to such a position with respect to said reciprocating slotting device that the transverse slots will coincide with the transverse creases, and means for restarting the conveyer.

13. In a machine for creasing and slotting blanks, a rotary creasing device for forming transverse creases in the blanks, a reciprocating slotting device for forming transverse slots in the blanks, a traveling conveyer for conveying the blanks from said rotary creasing device to said reciprocating slotting device, means, controlled by the blank in its movement, for stopping said conveyer when said blank has been brought to such a position with respect to said reciprocating device that the transverse slots will coincide with the transverse creases, and means for restarting the conveyer.

14. In a machine for creasing and slotting blanks, in combination, a rotary creasing device for forming transverse creases in the blanks, a reciprocating creasing device for forming longitudinal creases in the blanks, a slotting device for forming transverse slots in the blanks, and means for conveying the blanks to an operative position with respect to each of said devices in succession, and so that the transverse slots produced by said slotting device will coincide with the transverse creases produced by said rotary creasing device.

15. In a machine for creasing and slotting blanks, in combination, a rotary creasing device for forming transverse creases in the blanks, a reciprocating creasing device for forming longitudinal creases in the blanks, a reciprocating slotting device for forming transverse slots in the blanks, and means for conveying the blanks to rest in such a position with relation to said slotting device that the transverse slots will coincide with the transverse creases.

16. In a machine for creasing and slotting blanks, in combination, a rotary creasing de-

vice for forming transverse creases in the blanks, a reciprocating creasing device for forming longitudinal creases in the blanks, a reciprocating slotting device for forming transverse slots in the blanks, a conveyer for conveying the blanks to said slotting device, and means for stopping said conveyer when each blank has reached such a position with respect to the slotting device that the transverse slots will coincide with the transverse creases, and for subsequently restarting the conveyer.

17. In a machine for creasing and slotting blanks, in combination, a rotary creasing device for forming transverse creases in the blanks, a reciprocating creasing device for forming longitudinal creases in the blanks, a reciprocating slotting device for forming transverse slots in the blanks, a conveyer for conveying the blanks to said slotting device, and means, controlled by the blank, for stopping said conveyer when each blank has reached such a position with respect to the slotting device that the transverse slots will coincide with the transverse creases, and for subsequently restarting the conveyer.

18. In a machine for creasing and slotting blanks, in combination, a rotary creasing device for forming transverse creases in the blanks, a reciprocating creaser press for forming longitudinal creases in the blanks, a reciprocating slotting device for forming transverse slots in the blanks, means for actuating said creaser press and slotting device simultaneously, and a continuously progressing and intermittently operated conveyer for conveying blanks from said first-named creasing device to said creaser press and slotting device, said conveyer being adapted to support two blanks simultaneously in operative relation with said creaser press and said slotting device respectively.

19. In a machine for creasing and slotting blanks, in combination, a rotary creasing device for forming transverse creases in the blanks, a reciprocating creaser press for forming longitudinal creases in the blanks, a reciprocating slotting device for forming transverse slots in the blanks, means for actuating said creaser press and said slotting device simultaneously, a continuously progressing and intermittently operated conveyer for conveying the blanks from said first-named creasing device to said creaser press and said slotting device, said conveyer being adapted to support two blanks simultaneously at a distance apart corresponding with the distance between said creaser press and said slotting device, means for imparting movement to said conveyer, and means for stopping said conveyer when one of the blanks carried thereby is in proper position with relation to said creaser press and the other blank is in such position with relation to said slotting device that the transverse

slots will be coincident with the transverse creases formed by said first-named creasing device.

20. In a machine for creasing and slotting blanks, in combination, a rotary creasing device for forming transverse creases in the blanks, a reciprocating creaser press for forming longitudinal creases in the blanks, a reciprocating slotting device for forming 10 transverse slots in the blanks, means for actuating said creaser press and said slotting device simultaneously, a conveyer for conveying the blanks from said rotary creasing device to said creaser press and said slotting device, said conveyer being adapted to support two blanks simultaneously at a distance apart corresponding with the distance between said creaser press and said slotting device, means for imparting movement to 15 said conveyer, and means for stopping said conveyer when one of the blanks carried thereby is in proper position with relation to said creaser press and the other blank is in such position with relation to said slotting 20 device that the transverse slots will be coincident with the transverse creases formed by said rotary creasing device.

21. In a machine for creasing and slotting blanks, in combination, a creasing device for 30 forming transverse creases in the blanks, a reciprocating creaser press for forming longitudinal creases in the blanks, a reciprocating slotting device for forming transverse slots in the blanks, means for actuating said creaser press and said slotting device simultaneously, a conveyer for conveying the blanks from said first-named creasing device to said creaser press and said slotting device, said conveyer being adapted to support two blanks simultaneously at a distance apart corresponding with the distance between said creaser press and said slotting device, means for imparting movement to said conveyer, and means, controlled by the 35 blanks to be operated upon by said slotting device, for stopping said conveyer when one of the blanks carried thereby is in proper position with relation to said creaser press and the other blank is in such position with relation to said slotting 40 device that the transverse slots will be coincident with the transverse creases formed by said first-named creasing device.

22. In a machine for creasing and slotting blanks, in combination, a rotary creasing device for forming transverse creases in the blanks, a reciprocating creaser press for forming longitudinal creases in the blanks, a reciprocating slotting device for forming 50 transverse slots in the blanks, means for actuating said creaser press and said slotting device simultaneously, a conveyer for conveying the blanks from said rotary creasing device to said creaser press and said slotting device, said conveyer being adapted to sup-

port two blanks simultaneously at a distance apart corresponding with the distance between said creaser press and said slotting device, means for imparting movement to said conveyer, and means, controlled by the 70 blank to be operated upon by said slotting device, for stopping said conveyer when one of the blanks carried thereby is in proper position with relation to said creaser press and the other blank is in such position with relation to said slotting device that the 75 transverse slots will be coincident with the transverse creases formed by said rotary creasing device.

23. In a machine for creasing and slotting blanks, in combination, a pair of co-operating creaser-reels for forming transverse creases in the blanks, means for imparting rotation to said reels, a creaser press for forming longitudinal creases in the 80 blanks, a slotting device for forming transverse slots in the blanks, means for actuating said creaser press and said slotting device simultaneously once for every two revolutions of said creaser-reels, whereby said 85 creaser-reels have an operative and an idle rotation for each cycle of the machine, a conveyer adapted to support two blanks simultaneously at a distance apart corresponding with the distance between said 90 creaser press and said slotting device, means for stopping said conveyer when one of the blanks carried thereby has been brought into the proper position beneath 95 said creaser press, and the other blank has been brought into a position with respect to said slotting device that the transverse slots will coincide with the transverse 100 creases, and for subsequently restarting said conveyer, and means for transporting blanks successively from said creaser-reels to said conveyer.

24. In a machine for creasing and slotting blanks, in combination, a pair of co-operating creaser-reels for forming transverse creases in the blanks, means for imparting rotation to said reels, a creaser press for forming longitudinal creases in the blanks, a slotting device for forming transverse 115 slots in the blanks, means for actuating said creaser press and said slotting device simultaneously once for every two revolutions of said creaser-reels, whereby said creaser-reels have an operative and an idle rotation 120 for each cycle of the machine, a conveyer adapted to support two blanks simultaneously at a distance apart corresponding with the distance between said creaser press and said slotting device, means for imparting 125 movement to said conveyer, means for stopping said conveyer when one of the blanks carried thereby has been brought into the proper position beneath said creaser press, and the other blank has been brought into 130

- a position with respect to said slotting device that the transverse slots will coincide with the transverse creases, and for subsequently restarting said conveyer, means 5 for feeding a blank to said creaser-reels at each operative revolution thereof, and means for transporting blanks successively from said creaser-reels to said conveyer.
25. In a machine for creasing and slotting blanks, in combination, a pair of co-operating creaser-reels for forming transverse creases in the blanks, means for imparting rotation to said reels, a creaser press for forming longitudinal creases in the blanks, 10 a slotting device for forming transverse slots in the blanks, means for actuating said creaser press and said slotting device simultaneously once for every two revolutions of said creaser-reels, whereby said creaser-reels have an operative and an idle 15 rotation for each cycle of the machine, a conveyer adapted to support two blanks simultaneously at a distance apart corresponding with the distance between said creaser press and said slotting device, means for imparting movement to said conveyer, means, controlled by the blank about to be operated upon by said slotting device, for stopping said conveyer when one of the 20 blanks carried thereby has been brought into the proper position beneath said creaser press, and the other blank has been brought into a position with respect to said slotting device that the transverse slots will coincide 25 with the transverse creases, and for subsequently restarting said conveyer, and means for transporting blanks successively from said creaser-reels to said conveyer.
26. In a machine for creasing and slotting blanks, in combination a pair of co-operating creaser-reels for forming transverse creases in the blanks, means for imparting rotation to said reels, a creaser-press for forming longitudinal creases in the blanks, 30 a slotting device for forming transverse slots in the blanks, means for actuating said creaser press and said slotting device simultaneously once for every two revolutions of said creaser-reels, whereby said creaser-reels have an operative and an idle rotation for each cycle of the machine, a conveyer adapted to support two blanks simultaneously at a distance apart corresponding with the distance between said creaser press and said slotting device, means for imparting movement to said conveyer, means, controlled by the blank about to be operated upon by said slotting device, for stopping said conveyer when one of the blanks carried thereby has been brought into the proper position beneath said creaser press, and the other blank has been brought into a position with respect to said slotting device that the transverse slots will coincide with the transverse creases, and for subsequently restarting said
- conveyer, means for feeding a blank to said creaser-reels at each operative revolution thereof, and means for transporting blanks successively from said creaser-reels to said conveyer.
27. In a machine for creasing and slotting blanks, in combination, a rotary creasing device for forming transverse creases in the blanks, a creaser press for forming longitudinal creases in the blanks, a slotting device for forming transverse slots in the blanks, a conveyer adapted to support two blanks simultaneously, for conveying blanks into the proper positions with respect to said creaser press and said slotting device, 70 said conveyer extending forwardly of said creaser press, to an extent substantially equal to the distance between said creaser press and said slotting device, means for transporting blanks from said rotary creasing device to said conveyer so as to be carried forward thereby when the conveyer moves, and means for imparting intermittent movements, with intermediate pauses, to said conveyer, said movements being of an extent 75 substantially equal to the distance between said creaser press and said slotting device, whereby the blanks are carried by said conveyer successively first into operating position with respect to said creaser press and 80 then into operating position with respect to said slotting device.
28. In a machine for creasing and slotting blanks, in combination, a rotary creasing device for forming transverse creases in the 85 blanks, a creaser press for forming longitudinal creases in the blanks, a slotting device for forming transverse slots in the blanks, a conveyer adapted to support two blanks simultaneously, for conveying blanks 90 into the proper positions with respect to said creaser press and said slotting device, whereby the blanks are carried by said conveyer successively first into operating position with respect to said creaser press and 95 then into operating position with respect to said slotting device.
29. In a machine for creasing and slotting blanks, a pair of creaser-reels for forming transverse creases in the blanks, means for 100

- imparting rotation to said creaser-reels, a creaser press for forming transverse slots in the blanks, a slotting device for forming transverse slots in the blanks, means for actuating said creaser press and said slotting device simultaneously and so as to effect one operation thereof during two revolutions of said creaser-reels, whereby said creaser-reels have an operative revolution 10 and an idle revolution for each cycle of the machine, a conveyer adapted to support two blanks simultaneously, for conveying the blanks into the proper positions with respect to said creaser press and said slotting device, said conveyer extending forwardly of said creaser press to an extent substantially equal to the distance between said creaser press and said slotting device, means for feeding a blank to said creaser-reels at each operative revolution thereof, means for transporting blanks from said creaser-reels to said conveyer so as to be carried forward by said conveyer when the latter moves, and means for imparting intermittent movements with intermediate pauses, to said conveyer, said movements being of an extent substantially equal to the distance between said creaser press and said slotting device, whereby the blanks are carried by said conveyer successively first into operating position with respect to said creaser press and then into operating position with respect to said slotting device.
30. In a machine for creasing and slotting blanks, a pair of creaser-reels for forming transverse creases in the blanks, means for imparting rotation to said creaser-reels, a creaser press for forming longitudinal creases in the blanks, a slotting device for forming transverse slots in the blanks, means for actuating said creaser press and said slotting device simultaneously and so as to effect one operation thereof during two revolutions of said creaser-reels, whereby said creaser-reels have an operative revolution 10 and an idle revolution for each cycle of the machine, a conveyer adapted to support two blanks simultaneously, for conveying the blanks into the proper positions with respect to said creaser press and said slotting device, said conveyer extending forwardly of said creaser press to an extent substantially equal to the distance between said creaser press and said slotting device, means for feeding a blank to said creaser-reels at each operative revolution thereof, means for transporting blanks from said creaser-reels to said conveyer so as to be carried forward by said conveyer when the latter moves, and means for imparting intermittent movements with intermediate pauses, to said conveyer, said movements being of an extent substantially equal to the distance between said creaser press and said slotting device, whereby the blanks are carried by said conveyer successively first into operating position with respect to said creaser press and then into operating position with respect to said slotting device.
31. In a machine for creasing and slotting blanks, in combination, a rotary creasing device for forming transverse creases in the blanks, said rotary creasing device including rotating die-supporting devices and interengaging dies mounted on said device so as to be capable of adjustment according to the desired distance between the transverse creases, a pair of supporting frames, a pair of reciprocating creasing devices for forming longitudinal creases in the blanks, said reciprocating creasing devices being mounted one on each of said frames, a pair of slotting devices for forming transverse slots in the blanks, said slotting devices being mounted one on each of said frames, means for adjusting said slotting devices to cause the distance between the slots formed thereby to correspond with the distance between the transverse creases, means for adjusting said frames laterally to vary the position of the longitudinal creases, and means for conveying the blanks from said rotary creasing device to said reciprocating creasing devices and said slotting devices.
32. In a machine for creasing and slotting blanks, in combination, a rotary creasing device for forming transverse creases in the blanks including rotating die-supporting devices and interengaging dies mounted thereon so as to be capable of adjustment with relation to one another, a pair of supporting frames, a pair of reciprocating creasing devices for forming longitudinal creases in the blanks and mounted on said frames, a pair of reciprocating slotting devices for forming transverse slots in the blanks and mounted on said frames, a conveyer for conveying blanks into position first with relation to said creasing device and then with relation to said slotting devices, mechanism for arresting the movement of said conveyer when the blanks have reached the proper positions with respect to said reciprocating creasing devices and said slotting devices, a stop, adapted to be engaged and moved by the blank about to be operated upon by said slotting devices, for actuating said arresting mechanism, means for adjusting said slotting devices with respect to said stop and so as to cause the distance between the transverse slots to correspond with the distance between the transverse creases, and means for laterally adjusting said supporting frames so as to vary the positions of the longitudinal creases.
33. In a machine for forming transverse creases in blanks, the combination with a rotary creaser having transverse creasing members thereon arriving at operating position at timed intervals and forming trans-

- verse creases in individual blanks delivered thereto, of means for timing the movement of the individual blanks into the creasers with respect to the arrival of the creaser members at their operating position, comprising a blank supporting device, a removable stop engaged by the front edge of a blank to be fed into the machine, a feed roll moved into and out of operative relation with the blanks, means for imparting a gradually accelerated rotation to said feed roll to move the blanks into the rotary creasers when the stop is moved from the path of the blanks, and means timed with relation to the arrival of the creaser members at operative position for removing said stop from the path of the blanks and for moving said feed rolls into operative relation with the blanks.
34. In a machine for forming transverse creases in blanks, the combination with a rotary creaser having transverse creasing members thereon arriving at operative position at timed intervals adapted to form transverse creases in individual blanks passed therethrough, of means for delivering the individual blanks to the creasers in timed relation to the arrival of the creaser members at operative position, comprising a feed roll, a second feed roll movable toward and away from said first-named feed roll and adapted to grip a blank between itself and said first-named feed roll when moved toward the latter, means for causing one of said feed rolls to rotate and for increasing the speed of its rotation until its peripheral speed is substantially the same as that of said rotary creasing device, means for moving said second-named feed roll toward said first-named feed roll, when rotation of one of the feed rolls is about to be started, and means for subsequently moving said second-named feed roll away from said first-named feed roll.
35. In a machine for forming transverse creases in blanks, the combination with a rotary creaser having transverse creaser members thereon arriving at operative position at timed intervals, of means for timing the movement of the individual blanks into the creasers with respect to the arrival of the creaser members at their operative position, comprising a blank supporting device, a removable stop engaged by the front edge of the blanks, a feed roll, a second feed roll movable toward and away from the first feed roll and gripping the blanks between itself and the first feed roll when moved toward the latter, means for causing one of the feed rolls to rotate and for increasing the speed of its rotation until its peripheral speed is substantially the same as that of the rotary creasers, means for subsequently stopping the rotation of said feed roll, means for moving said stop from the path of the blanks and moving the movable feed roll toward the other, and means for subsequently moving the movable feed roll away from the other roll and returning the stop to its position ready for engagement by another blank.
36. In a machine for forming transverse creases in blanks, the combination with a rotary creasing device comprising a pair of rotatably mounted supports and interengaging creasing dies carried by said supports for forming transverse creases in individual blanks and timed to arrive at operative position at predetermined intervals, of means for delivering individual blanks to said creasing device at timed intervals comprising a feeding roll, a second feed roll movable toward and away from the first feed roll and adapted to grip the blank between itself and the first feed roll when moved toward the latter, means for causing one of the feed rolls to rotate and for increasing the speed thereof until its peripheral speed is substantially the same as that of the rotary creasing device, means for subsequently stopping the rotation of said feed roll, means for moving said movable feed roll toward the other roll when the rotation of one of the rolls is about to be started, and means for subsequently moving the movable roll away from the other roll.
37. A device of the character described comprising a pair of supporting frames arranged side by side, rock shafts mounted on

said frames, arms having one end supported from said shafts and the other end slidably supported on said frames, arms carried and operated by said rock shafts, coöperating dies carried by said arms, and means for rocking said rock shafts simultaneously.

39. A device of the character described comprising a pair of supporting frames arranged side by side, means for adjusting 10 said supporting frames toward and away from each other, rock shafts mounted in said frames, arms having one end supported from said shafts and the opposite end slidably supported on said frames, arms carried and 15 operated by the rock shaft, coöperating dies carried by said arms, and means for operating said rock shafts simultaneously.

40. A device for forming creases in blanks, comprising a pair of supporting 20 frames arranged side by side, dies supported on said frames, rock shafts mounted on said frames, arms carried by said rock shafts, creaser beams carried by said arms, dies carried by said creaser beams and coöperating 25 with said first-named dies, cranks carried by said rock shafts, a drive shaft, eccentrics carried by said drive shaft and connected with said cranks, means for locking said cranks and said eccentrics in a fixed position 30 with relation to each other, and means for adjusting said support frames toward and away from each other.

41. In a device for forming longitudinal creases and transverse slots in blanks, a pair 35 of support frames, creaser dies supported on said frames, slotter dies supported on said frames, rock shafts mounted on said frames, creaser arms carried by said rock shafts, dies carried by said creaser arms and co- 40 operating with said first-named creaser dies, slotter arms secured at their rear ends to said rock shafts and operated thereby, slotter blades carried by said slotter arms, and coöperating with said slotter dies, means for 45 imparting a rocking movement to said rock shafts, cranks carried by said rock shafts, a

drive shaft, eccentrics carried by said drive shafts and connected with said cranks, means for locking said cranks and said eccentrics in a fixed relation with one another, 50 and means for adjusting said support frames toward and away from each other.

42. A device of the character described comprising a pair of oppositely disposed supporting frames, of rock shafts carried 55 by said frames, arms supported at one end on said shafts and having their opposite end slidably supported on said frames, arms carried and operated by said shafts, coöperating dies carried by said arms, means 60 for adjusting said arms along said shafts, and means for adjusting said frames toward and away from each other.

43. A device for forming longitudinal creases and transverse slots in blanks, comprising a pair of oppositely disposed support frames, rock shafts carried by said support frames, creaser dies resting on said support frames, creaser arms carried by said rock shafts, creaser dies carried by said 70 creaser arms and coöperating with said first-named creaser dies, slotter dies resting on said support frames, slotter arms secured at their rear ends to said rock shafts and operated thereby, blades carried by said slotter 75 arms, cranks carried by said rock shafts, a drive shaft, eccentrics carried by said drive shafts, and connected with said cranks, means for locking said eccentrics and said cranks in a fixed position with relation to 80 each other, means for adjusting said support frames toward and away from each other, and means for adjusting said slotter arms longitudinally on said rock shafts.

In witness whereof, I have hereunto subscribed my name in the presence of two witnesses.

KARL I. HERMAN.

Witnesses:

M. REYNOLDS,
C. E. KANE.

It is hereby certified that in Letters Patent No. 1,219,941, granted March 20, 1917, upon the application of Karl L. Herman, of Chicago, Illinois, for an improvement in "Box-Blank-Making Machines," errors appear in the printed specification requiring correction as follows: Page 9, line 2, for the word "blanks" read *blank*; page 13, line 1, for the word "brake" read *blank*; and that the said Letters Patent should be read with these corrections therein that the same may conform to the record of the case in the Patent Office.

Signed and sealed this 8th day of May, A. D., 1917.

[SEAL.]

R. F. WHITEHEAD,
Acting Commissioner of Patents.

Cl. 93—58.
